JOHN ERICKSON AND CHARLES J. ERICKSON, OF CHICAGO, ILLINOIS, ASSIGNEES, BY
MESNE ASSIGNMENTS, TO AUTOMATIC ELECTRIC INC., OF CHICAGO, ILLINOIS, A
CORPORATION OF DELAWARE.

SWITCHING APPARATUS FOR TELEPHONE-EXCHANGE SYSTEMS.

Application filed October 16, 1905, Serial No. 282,984. Renewed June 15, 1907. Serial No. 379,180.

Our invention relates to electrical switching machinery and apparatus in general, but more particularly to the switching machinery and apparatus employed in automatic or semi-automatic telephone systems, and through the medium of which the subscribers are enabled to establish connection between their lines without the assistance of switchboard operators—or at least to accomplish the operation of a certain proportion of the exchange or switchboard apparatus without the assistance of switchboard operators—and especially to automatic or semi-automatic telephone systems of that character in which the subscribers are provided with switching means for transmitting one or more electrical impulses—as by momentarily grounding either one or both sides of the line—for operating one or more electrically-propelled switching machines at the exchange or central station. In telephone exchange systems of this character, whether automatic or only semi-automatic, it is desirable to provide the exchange with a number of trunk-lines or other connections which are common to all the subscribers, or to all the members of a certain group of subscribers. For example, the exchange may be of considerable size and capacity, and may be divided into groups of one hundred subscribers each, and for each group of subscribers there may be allotted ten trunk-lines any one of which can be used by any subscriber in his group in establishing connection with any other subscriber of the same exchange, or with any subscriber of any other exchange having trunk-line connection with the exchange to which the said group of subscribers belongs. If the exchange to which this group of subscribers belongs is quite large, it may be necessary for each calling subscriber to select from two or more groups of trunk-lines before obtaining connection with the called subscriber's line—that is to say, it may be necessary for the calling subscriber to first automatically select an idle trunk-line from the first group, to then automatically select an idle trunk-line from a second group of trunk-lines, and to then perhaps automatically select an idle trunk-line from a third group, thus putting in use three trunk-lines before connection is finally established directly with the line of the called subscriber.

In each case, of course, any idle trunk-line in the first group will serve the purposes of the calling subscriber, and this is true of the second and third groups, and of the fourth and fifth groups, if the exchange is very large and includes a great number of subscribers. In telephone systems of this character which are very small, or which are of considerable size and operated only on a semi-automatic basis, it may then become necessary for each calling subscriber to automatically select only one trunk-line, or other similar connection, before the operation occurs by which the final connection is established directly with the called subscriber's line; but in any event, and regardless of whether the exchange is large or small, or automatic or semi-automatic in character, it is desirable that the central station or exchange apparatus be so constructed and arranged that any calling subscriber will necessarily and automatically select at least one idle trunk-line, or other suitable idle common connection, before connection is finally established with the line of the called subscriber; for with such arrangement, the calling subscriber actually operates or controls either all or a part of the machinery or apparatus by which his line is connected with the line of the called subscriber, thus dispensing with either all or a certain proportion of the usual switchboard operators, and materially reducing the time in which the calling subscriber either obtains the desired connection or gets a signal indicating that the called subscriber's line is busy.

In an automatic telephone system, the switching machine which picks out or selects the called subscriber's line and makes connection directly therewith is commonly known as a "connector"; and if the exchange is large enough to require it, these "connectors" are then arranged in groups and employed on a percentage basis—that is to say, they can be divided into groups of ten, and each group of "connectors" can be allotted to a group of one hundred subscribers. In such case, it is desirable to provide other switching machines which are commonly known as "selectors," and which are employed by calling subscribers in picking out idle trunk-lines. If the exchange is not very large, it will only be necessary for each calling subscriber to use one "se-

lector" and one "connector" in establishing connection with any called subscriber's line; but if the exchange is larger, it may then become necessary for any calling subscriber to operate a "first-selector," then a "second-selector," and finally a "connector," before establishing connection with the called subscriber's line. The "first-selectors" can each be allotted to a subscriber's line, thus making the total number of "first-selectors" equal to the total number of subscribers in the exchange; then if "second-selectors" are necessary, these intermediate "selectors" or switching machines can be employed on a percentage basis, thus, for example, making the total number of "second-selectors" only one-tenth of the total number of subscribers; and it will be understood that these "selectors" are preferably divided into groups. In any event, a "selector" is preferably a switching machine of such character that it can be controlled by the calling subscriber to the extent of causing it to pick out any particular group of switching machines, either "selectors" or "connectors," as the case may be, and which, after so doing, escapes momentarily from the control of the calling subscriber and proceeds automatically and by itself to pick out the first idle switching machine which it encounters in its operation, and which it finds in the group of switches selected by the calling subscriber. As distinguished from this, however, a "connector" is controlled by the calling subscriber throughout its operation of picking out and making connection with the called subscriber's line, inasmuch as the calling subscriber must not only select a certain group subscribers' lines, but must then cause the "connector" to select and make connection with a certain one of such group of subscribers' lines. Take, for example, a system in which there are only "first-selectors" and "connectors," the exchange being of such size and capacity that second and third or other intermediate "selectors" are not necessary. In such case, the "first-selectors" may be each allotted to a single subscriber's line, and the "connectors" may be arranged in groups and employed upon a basis of ten per cent of the total number of subscribers, so that there will be only one-tenth as many "connectors" as the total number of subscribers' lines entering the exchange. With such arrangement, and calling subscriber will first operate his "first-selector" in such manner as to cause the same to pick out the particular group of "connectors" in which the called subscriber's line terminates; but after this, and as it is immaterial which one of these "connectors" is employed, the "selector" momentarily escapes from the control of the calling subscriber and proceeds automatically and by itself to pick out the first idle trunk-line which it encounters in its operation, and which it finds in the group of trunk-lines running to the group of "connectors" selected by the calling subscriber. After this, the calling subscriber then operates the selected "connector" in such manner as to cause it to select the particular group or division of subscribers' lines to which the called subscriber's line belongs, and the "connector" is capable of then resting in this position, or at this point, in its operation. Having thus caused the selected "connector" to pick out the desired group of subscribers' lines, the calling subscriber can then again operate the "connector" for the purpose of causing it to both select and make connection with the exact or particular subscriber's line with which connection is desired; thus, in a "connector," the selection of a group of lines and the selection of a certain number of such group are both definite in character. In a "selector," however, as explained, the selection of any group of lines is always definite in character, but the selection of any member of such group is not definite, at least not in the sense that the calling subscriber wants connection with a certain one of such lines and will not accept any other. In other words, the calling subscriber must always select the exact or particular group of lines, whether it be a group be a group of trunk-lines or a group of subscribers' lines, but is not called upon to select a certain line until after the selection has been made of the particular or desired group of subscribers' lines, and then, of course, the selection from this group of a certain subscriber's line must be definite in character, as the calling subscriber wants a certain subscriber's line and no other. In systems of this character, and particularly in large exchanges, it has been found desirable to reduce the "first-selectors" to a percentage basis, thus making the total number of "first-selectors" considerably less than the total number of subscribers' lines entering the exchange. With this arrangement, both the "selectors" and "connectors" can be employed on an economical percentage basis. The connectors may be made common to all the subscribers, and the selectors may be divided into groups corresponding to the groups of subscribers, the selectors of each group being common to all of the subscribers of the group. Under such circumstances, it is customary to provide each subscriber's line with what is commonly known as an individual-switch—that is to say, a comparatively simple and economical switching device by which a subscriber can automatically select an idle "first-selector." For example, the subscribers' lines can be arranged in groups of

one hundred, each line terminating in an individual switching device, and there being only ten "first-selectors" allotted to this group of one hundred subscribers' lines; and it has been demonstrated that these one hundred individual-switches and ten "first-selectors" constitute a more economical and more satisfactory arrangement than the one hundred "first-selectors" which would, with the old arrangement, ordinarily be allotted to such a group of subscribers, for each individual switching device may obviously be very simple in construction and operation, inasmuch as it is never called upon to do anything but merely automatically select one of the ten "first-selectors," thus dispensing at this time with the operation which corresponds to the first portion of the operation of an ordinary "selector," and practically reducing the whole operation of the individual-switch to a basis where it corresponds with only the second or automatic portion of the operation of a "selector." Consequently, in systems employing individual switching machinery, the calling subscriber first automatically selects an idle "first-selector," and then selects a second and even a third "selector," if the exchange is quite large, before finally and automatically selecting an idle "connector," and before causing such "connector" to pick out and make connection with the particular line of the called subscriber; but, as stated, this arrangement has been found to be much more economical, and to give as good and even better results, than the old arrangement in which a regular "first-selector" is provided for each subscriber's line. The current for operating the switching machinery at the exchange is preferably supplied from a storage battery or other suitable centralized source of supply located at the central station, while the current for talking purposes may be supplied from local batteries or from the said common source; and the current for ringing the bells at the subscribers' stations is preferably supplied from an alternating-current dynamo or other suitable source at the exchange or central station. As explained, the subscribers are each provided with the switching devices for operating the switching machinery at the exchange or central station. In some cases, the arrangement is such that the calling subscriber in removing his receiver from the usual switch-hook automatically grounds one side of his line, and thereby brings about the transmission of an electrical impulse which operates the individual switching device. After this, the calling subscriber operates his calling device in such manner as to transmit the required number of impulses—that is to say, the impulses which represent the number of the called subscriber, and which bring about the operation of the switching machinery that results in the establishment of connection with the called subscriber's line. When this has been done, the calling subscriber then presses a key or button, and this act results in a temporary transmission or supply of ringing-current to the called subscriber's line, sufficient to ring his bell. Many kinds of devices are, however, employed at the subscribers' stations of automatic telephone exchanges for enabling the subscribers to themselves operate either all or a portion of the exchange apparatus or switching machinery at the central station.

Generally stated, the object of our invention is the provision of an improved and highly efficient automatic or semi-automatic telephone system of the foregoing general character.

Special objects of our invention are the provision of a subscriber's individual-switch mechanism which is subject to a selective operation each time that some other individual-switch in the same group is put in use by its allotted subscriber, whereby all idle individual-switches always have an idle trunk-line selected and held in readiness for the next subscriber making a call, and thus making it unnecessary for any calling subscriber to do anything more than simply cause his individual-switch mechanism to complete the trunk-line connection which has already been selected for him—that is to say, which was selected for him by the subscriber making the last call just ahead of him; the provision of a subscriber's individual-switch mechanism of such character that its trunk-selecting elements are, when at rest, always in position for establishing connection with the idle trunk-line next to be used, regardless of whether or not the individual-switch is being used by its allotted subscriber, and whereby each subscriber in this particular group not only causes his individual-switch to close the connection already selected for him when he decides to call some other subscriber in the exchange, but also causes the trunk-selecting elements of all individual-switches in such group to advance sufficiently to select the next idle trunk-line, thus keeping all individual-switches in constant condition for affording instant connection with an idle trunk-line, providing, of course, that the trunk-lines are not all busy; the provision of an improved arrangement involving a group of subscribers' individual-switch mechanisms, and involving also a switch-operating machine which is common to all of said switch mechanisms, each individual-switch having trunk-selecting means adapted to be operated by the said switch-operating machine, and each individual-switch having in addition means whereby its allot-

ted subscriber may appropriate or close connection with any trunk-line selected by the said trunk-selecting means; the provision of a subscriber's individual-switch of such character that both the trunk-selecting and trunk-connecting means thereof may remain wherever they happen to be when the subscriber is through using his telephone, thus making it unnecessary to restore the individual-switch to any so-called normal position, or to do anything more to said switch than simply de-energize one or more of its electro-magnets or relays when the subscriber hangs up his receiver for the purpose of disconnecting his line from the trunk-line which he was using; the provision of a subscriber's individual-switch mechanism of such character that should its allotted subscriber cause it to close connection with the already selected trunk-line, and then for any reason fail immediately to begin calling the other subscriber, it will proceed immediately to advance and make connection with the next idle trunk-line if, in the meantime, some other subscriber calls in and makes a call and secures connection with the said already selected trunk-line, thus giving each subscriber the means whereby he may, at least under certain conditions, substitute an idle trunk-line for the trunk-line already connected with some other subscriber's line; the provision of an improved construction and arrangement of subscribers' individual-switches and a switch-operating machine common to all of said switches of such character that each individual-switch may, when put in use for connective purposes, remain in operative connection with the said switch-operating machine, and whereby the trunk-selecting means of each individual-switch may, even while the switch is in use, remain subject to a selective operation each time another trunk-line is put in use; the provision of improved trunk-selecting machinery adapted for use in various connections, but adapted more particularly for use by telephone subscribers for automatically selecting an idle trunk-line or other connection preliminary to the final establishment of connection with the called subscriber's line, and regardless of the manner in which such final connection is accomplished; the provision of a plurality of trunk-lines or other suitable connections, together with trunk-selecting and connecting means of such character that the mechanism is, when at rest, always mechanically set for the establishment of connection with an idle trunk-line as soon as the trunk-connecting means is operated, and whereby the trunk-connecting means when operated will always act in accordance with the condition at that time of the trunk-selecting means, and will always afford connection with the particular trunk-line which has been mechanically

selected by the said trunk-selecting means; and the provision of certain details and features of improvement tending to increase the general efficiency and serviceability of automatic or semi-automatic telephone exchange apparatus of this particular character. 70

To the foregoing and other useful ends, our invention consists in matters hereinafter set forth and claimed.

Fig. 1 is a diagrammatic representation of one of the sub-stations A comprised in our system and connected to its corresponding individual switching device C through the medium of the vertical and rotary line-conductors 2 and 3. To the right of said individual-switch is shown one of the "first-selectors" D, with which said individual has temporarily connected the line of sub-station A. Below the individual-switch C is shown the individual-shaft controlling-apparatus E which belongs to the common shaft of the group of individuals of which the individual-switch C is a member. Again, to the right of the "first-selector" D is shown the "connector" F, which is one of a group to which the subscriber's line has been extended by the selective operation of the "first-selector" D. 75 80 85 90 95

In Fig. 2 the individual-switch H of the called line is similarly represented and is shown connected by the conductors 4 and 5 with the called sub-station J, designated as #220. Therefore, Figs. 1 and 2, taken together, illustrate the sub-station A connected with a second sub-station J through the medium of one of the individual-switches C, the "first-selector" D, the "connector" F, and the second individual-switch H, which last constitutes the terminal of the line-conductors that lead to the called sub-station J. 100 105

Fig. 3 similarly represents the mechanisms and circuits of the individual-switch C and the common controlling mechanism E, said individual switch being shown temporarily connected with trunk-lines that lead to a "first-selector" D. 110

Fig. 4 is a side elevation of the individual-switch supported upon an angle-iron base, showing the operating magnets and the individual-arm. 115

Fig. 5 is a detail view of the line-relays by means of which the individual-switch C is controlled, said relays being mounted upon a supporting-plate. 120

Fig. 6 shows the switching and bridge-cut-off relays that control certain internal circuits in the individual-switch, and which are mounted upon the same plate with the line-relays shown in Fig. 5. 125

Fig. 7 is a top view of the relay supporting bridge.

Fig. 8 is a front view of the shaft-controlling mechanism comprising the clock-spring motor device, the automatic winding mecha- 130

nism, and the escapement that regulates the rotation of the shaft with which it is associated.

Fig. 9 is a partial section of the clock-spring winding device on line 9—9 in Fig. 8, looking to the left.

Fig. 10 is a similar view of the shaft escapement mechanism taken on line 10—10 in Fig. 8, looking to the right.

Fig. 11 is a top view of the escapement mechanism and a private-disk which takes part in the rotation of the shaft to which it is attached, both of which are instrumental in controlling the rotation of said shaft, the one mechanically and the other electromagnetically.

Fig. 12 is an end view of the individual-switch C.

Fig. 13 shows the left extremity of the shaft common to the group of individuals to which individual C belongs, carrying certain details among which is the clock-spring arrangement belonging to the said shaft, which spring, being kept constantly wound automatically, maintains the shaft in readiness for instant movement.

Fig. 14 shows a segment of the automatic winding device which is caused to be energized at each revolution of the shaft, through the medium of a lever attached to the section of shaft shown in Fig. 13.

Fig. 15 shows the end of said lever which carries a wedge for tripping certain devices hereinafter explained.

Fig. 16 is a section through the shaft and private-disk, showing the construction of said private-disk and the accompanying wiper.

Fig. 17 is a diagrammatic perspective view of the "first-selector" D.

Fig. 18 is a similar representation of the "connector" F.

Although various batteries are represented, there may be, however, but one battery B having preferably its positive pole grounded. The individual-switch is, as shown in the drawings, built upon a suitable frame 10 which is very clearly shown in Fig. 4. Any suitable number of these individuals may be mounted side by side upon the same support. Fig. 12 shows one of the individuals in place upon an angle-iron 11, and others may be placed on either side, with a shaft 12 common to all. The frame 10 of the individual-switch C (Fig. 4) supports the relay-bridge 13, which latter is secured to the former by bolts that pass through the holes 14. Upon this bridge the individual-line-relays 15 and 16, the switching-relay 17, and the bridge-cut-off-relay 18, also shown in Figs. 5 and 6, are attached by screws 19 that pass through the holes 20. Just below the bridge 13 the locking-magnet 21 is attached by the screw 22 to an angle-piece 23 (Fig. 4), said angle-

piece being secured to the frame by the screws 24. This locking-magnet is provided with an armature 25 that is pivoted to a post 26 which rises from the walls of the switch-frame. The end of this armature is in juxtaposition to the pole-piece of the magnet 21, and its other or downwardly-extending end is provided with a notch, the object of which will hereinafter be disclosed. Said armature is normally held away from the magnet-pole-piece by a retracting-spring 27, one end of which latter is secured to the lower end of said armature, and the other end of which is secured to the switch-frame. On the same frame, below the locking-magnet 21 and at right angles to the same, the release-magnet 28 is secured by the screw 29 to the angle-piece 30, which latter is secured to the switch-frame by the screws 31. This magnet also is provided with an armature 32 that serves as a lever of the third class, and which is pivoted at its end so as to cross the armature 25 of the locking-magnet at approximately right angles. Just at the point of crossing, the former armature 32 has a small lug 33 against which the latter armature 25 is normally held by the retracting-spring 27. These two armatures are so adjusted that when the armature 32 is attracted by the magnet 28, the notch at the end of the armature 25 then falls over the said lug 33 on the armature 32, thereby locking the latter against the pole-piece of the magnet 28, and away from the rack-segment 40 carried on the wiper-carrier 41. This last armature 32 also is normally held away from its magnet-pole-piece by the retracting-spring 42, one end of which is attached to the forward part of the armature, and the other end to the switch-frame. A small section 43 of the front extremity of said armature 32 is bent at right angles so as to extend upward, the object of which will be hereinafter disclosed. The wiper-carrier 41 and the cam-drag 44, which go to make up the individual-arm, are shown in Fig. 4. The two said component members are pivotally secured by the bolt 45 which is screwed to the switch-frame and which holds the said members 41 and 44 so that one may move independently of the other under certain conditions. In other words, if the wiper-carrier 41 is locked in one position in engagement with one particular bank-contact, and if the cam 46 is revolved by the shaft 12, the cam-drag 44 will be moved towards the outer extremity of said cam without disturbing the position of the wiper-carrier 41, and, of course, leaving the arm as a whole no longer straight. On the switch-frame, just to the right of the cam-drag 44, there is a ratchet-catch 47 which is pivoted near its rear end to a screw 48. Said ratchet, by means of the retracting-

spring 49, one end of which latter is fastened to the switch-frame, the other end to a lug in the rear of said ratchet, is kept normally against the stop-pin 50. Furthermore, said ratchet has loosely secured to it at its front end a light pin 51 which passes loosely through an opening in the armature 32. Said pin is provided on the end beyond the armature with a head 52, so that when the armature 32 is attracted by the release-magnet 28, the ratchet 47 also is then drawn down. It should be understood that the pin 51 is not tightly associated with said armature. On the cam-drag 44 there is located a pin 53 which is, when the cam rotates and the cam-drag is driven out to the limit of the same, caught by the ratchet 47, at which time said drag 44 is locked. Being once locked in said position, it is evident that the cam may continue to rotate, but it will no longer be encumbered with the friction of said drag upon its surface. Assuming the wiper-carrier 41 to be in the position indicated in full lines (Fig. 4), and the cam-drag to be locked by the ratchet 47, as indicated by the dotted lines, if the armature 32 be attracted by the release-magnet 28, the ratchet 47 through the medium of the pin 51 will be drawn to a position indicated by the dotted lines, and the drag 44 will be permitted to fall to the position shown in full lines. The means that tend to restore the individual-arm to a straightened position consist of two springs 44^a and 54. The ends of the latter are held by the pins 55 and 56, the body of said spring being coiled beneath the head of the screw 45, as very clearly shown in Fig. 12. Of course, it is through the medium of the armature 32 and rack-segment 40 that the wipers 57, 58 and 59 may be locked in any one position, there being a ratchet-tooth for each position that the wipers may assume. When the armature 32 is in its normal position the end 43 falls into the notches in the segment 40 and holds the wiper-carrier in whatever position it is caught. It was stated that if the release-magnet 28 were energized the release-armature 32 would be attracted and that the armature 25 through the medium of the lug 33 would lock said release-armature 32 against the pole-piece of the release-magnet. Under these conditions it is evident that the wiper-arm 41 and, therefore, the wipers 57, 58 and 59 are free to move wherever taken by the cam 46. This is true, of course, by reason of the fact that the cam-drag 44 is driven to the right of the cam, and the wiper-carrier 41 is bound to follow with the pin 60 resting against the cam-drag, because of the tension in the spring 54. The wiper-carrier can be locked again by energizing the locking-magnet 21, which latter will attract the armature 25 and thereby remove the locking end from the lug 33, thus permitting the spring 42 to draw the armature 32 into engagement with the ratchet-teeth 40. Of course, it will be understood that the bank-contacts shown at 61 (Fig. 3) are comprised in a bank more clearly shown at 61 in Fig. 4. The cam 46, being attached to the shaft 12, is operated by the same mechanism that controls the shaft. In Fig. 13 one end of the shaft 12 is shown as having secured to it the clock-spring device with a clock-spring 62 which furnishes motive power for rotating the shaft. A hub 63 that is rigidly secured to the shaft by the screw 65 carries a collar 64. A cup 66 fits rotatively over said hub and against said collar. This cup carries the spring 62, one end of which is secured to the hub and the other (the outer end) to the cup 66. A cover 67 is clamped over the cup and held against the hub 63 by the collar 68 which is fastened to the shaft by the screw 69. Said cover-holder does not interfere with the rotation of the cup upon the hub 63. As shown in Fig. 9, the outer circumference of the cup 66 is provided with ratchet-teeth that are more clearly shown in Fig. 14. The coil-spring 62 is tightened by the rotation of said cup through the medium of the ratchet and pawl device controlled by the winding-magnet 75, which latter is provided with an armature 76 that vibrates about an axis passing through the pivots 77 and which is supported upon a shelf 75^a that extends between the supporting members 90 and 117 (Fig. 8). The armature of the winding-magnet is normally held away from the pole-piece of the winding-magnet by a spring 78, which latter is riveted to the lug 79 that projects above said armature and to the rear thereof. Said spring may be regulated by a screw 80 with which it engages and which is fastened to the frame 81 of the winding-magnet upon which the armature is pivoted. To prevent said armature from being given too high an angle, a piece 82 is riveted to the upper part of the armature, with one portion protruding to the rear and extending down so that when the armature reaches a certain height said protruding portion strikes the magnet-frame 81. Furthermore, the armature carries an extended arm 83 at the end of which there is provided a finger 84 which is designed to engage with a set of circuit-breaking springs 85, 86 and 87 that are supported from the shelf 75^a. The object of this latter mechanism will be fully described. This extending arm supports near its center a pawl-piece 88 one end of which is pivoted on said arm, and the other end of which engages with the ratchet-teeth on the surface of the clock-spring-cup 66. Said

pawl 88, by means of a spring 89, is drawn toward the said ratchet-teeth. Upon a supporting-frame 90, which is secured to the angle-iron 11, and which receives one end 5 of the shaft 12, there is fastened an angle-plate 91 (Fig. 8) which extends as far as the under part of the cup 66 (Fig. 9). On the end of said angle-piece a second pawl 92 is pivotally secured, which engages 10 with the ratchet-teeth by a spring 93 which also has one end fastened to the end of the said supporting piece. The object of this pawl, which is pivoted to the screw 94, is to retain the cup-spring in its wound condition. For instance, when the winding-magnet 75 is energized the armature 76 is 15 attracted and the pawl 88 rotates the cup 66 in such a direction as to tighten the spring 62. Whatever advancement is given 20 to the cup by the pawl 88 is retained by the second pawl 92, which latter prevents said cup from revolving in a backward direction.

When the armature of the winding-magnet is released the pawl 88, upon returning to its normal position, passes over one or more of the ratchet-teeth on said cup and stands in readiness to turn the cup again when the winding-armature 76 is again attracted. Referring again to Fig. 8, it will be noticed that between the cup 66 and the supporting-frame 90 there is a crank 95 on the shaft 12. It will be noticed also that the cup 66 on the side nearest this crank has a wedge-shaped piece 96 which is more clearly shown in Fig. 14. Now, as the shaft is rotated by the clock-spring, the said crank 95 eventually strikes a bell-crank-piece 97 provided with the wedge 98, shown in Fig. 15. This bell-crank 97 is pivoted on the projecting angle piece 91 to the screw 99, and the spring 100 imparts a rotation to it through the arm 101, in a certain direction. Rotation beyond a certain point is checked by the pin 102 on the angle piece 91, which pin the arm 103 meets as it moves along. As the crank 95 continues to rotate, the wedge 98 continues to advance and eventually rotates the bell-crank 97 in a 45 backward direction by pressing on the arm 101, thus closing the two springs 100 and 104 which are supported on the frame 90 and insulated therefrom. Near the right extremity of the bell-crank-arm 103 a ratchet piece 105 is pivoted to the support 106. One end of said ratchet is held near the face of the cup 66 that carries the wedged projection 96 by the spring 107. Said ratchet is prevented from rubbing on the face of the cup by a pin 108 driven into the member 91. Just after the bell-crank is rotated enough to bring the springs 100 and 104 into contact, the arm 103 of said bell-crank then drives the ratchet-catch 105 back against the tension 50 of the spring 107. The construction of the end of said bell-crank-arm, and of the ratchet-head, is such that when the bell-crank-arm clears the angled head of the ratchet it is locked by the same, such a 55 position being indicated by dotted lines. It should be borne in mind that as soon as the springs 100 and 104 are brought into contact, a circuit is then closed through the winding-magnet 75, which latter is intermittently energized at regular intervals, so that the ratchet-arm 88 proceeds to wind up the cup-spring 62. The winding-magnet continues to operate until the cup is rotated once and the wedge-shaped piece 96 comes 60 into engagement with the ratchet 105. Said ratchet is then drawn against the pressure of the spring 107, and the bell-crank is allowed to return to its normal position against the stop-pin 102 by reason of the tension of the spring 100. As soon as the ratchet-catch 105 clears the end of the arm 103, the circuit through the springs 100 and 104 is broken, and the winding-magnet ceases to operate until the circuit-closing-crank 95 revolves once more. The method by which the intermittent operation of the winding-magnet 75 takes place is as follows: When the springs 100 and 104 are 65 brought together, the circuit through said magnet 75 is completed and its armature 76 is attracted. The finger 84 passes on the side of the spring 87 next to the magnet 75, thus flexing the interrupter-springs 85, 86 and 87 to the left (Fig. 9). As soon as the finger 84 clears the end of the spring 87, the latter returns to its normal position, breaking contact with the spring 85, which latter cannot return because the finger 84, after clearing the end of the spring 87, through the medium of the spring 86, retains the spring 85 out of its normal position until the armature 76 is released. When the connection between the springs 85 and 87, which are included in the energizing-circuit of the magnet 75, is broken, the armature 76 is then drawn back by the tension in the spring 78, and as soon as the finger 84 passes out of the way the interrupter-springs 85 and 87 re-engage, thus 70 once more energizing the winding-magnet 75. Obviously, each time the armature 76 is drawn down the cup 66 is rotated and the spring 62 is wound. The repetition of the attraction of the armature 76 continues to take place periodically as long as the springs 100 and 104 are kept closed together. It will be understood, of course, that the shaft 12 carries as many cams as there are individual-switches in the group to which the individual-switch G belongs, and one winding apparatus of the type described is sufficient for one such group. On the same shaft there is mounted the private-disk 115 that comprises as many 75 80 85 90 95 100 105 110 115 120 125 130

segments as there are contacts in the individual-bank 61, and, therefore, as many as there are "first-selectors" identified with the group of individuals of which the individual C is a member. This private-disk works in conjunction with the escapement device that comprises the escapement-magnet 116 which controls the position of the shaft. This magnet is shown clearly in Fig. 10. The shaft which passes through the supporting-frame 117, which latter is fastened to the angle-frame 11, has attached to it a star-wheel 118 which normally engages with the armature 119 of the escapement-magnet 116. Said escapement-magnet is mounted upon an angle-piece 120 that is secured to the frame 117. The escapement-armature is pivoted on the end of the escapement-magnet-frame 121, and is normally kept away from the pole-piece of this magnet by a spring 122 which is riveted to the magnet-frame. This spring exerts a pressure on the ratchet side of the escapement-armature, between the pivots 123 and the star-wheel 118. Each time the escapement-magnet becomes energized, the hook end 124 of the escapement-armature disengages from the star-wheel and permits the shaft to rotate in the direction indicated by the arrow. The segments of the private-disk are insulated from each other, and a wiper 125, which is also attached to the shaft, slides over the commutator-segment as the shaft rotates. This wiper is in electric connection with the metallic hub 126 which is also insulated from surrounding parts. A brush 127, attached to the angle-iron support 128, is in constant contact with the said metallic hub and, therefore, in constant electric connection with the wiper 125. It is clear that the angled piece 128 is secured to the member 120. Said wiper 125 (Fig. 3) is shown connected with the segment 433, and both are comprised in the circuit which energizes the escapement-magnet. Of course, as the shaft 12 rotates, the private-disk-wiper passes from one commutator-segment to another. In Fig. 8 a section of the magnet-frame is shown cut away to give a view of the escapement-magnet. In front of this magnet the star-wheel is shown, and to the right of the star-wheel is the private-disk-wiper fastened to the shaft. Just at the right of the private-disk-wiper, and attached to the frame, is the private-disk through the center of which passes the shaft 12. It is evident, then, referring to Fig. 10, that if the escapement-magnet becomes energized for a very short period, the escapement-armature will be drawn down for an instant, drawing the pawl extremity of said armature out of engagement with the tooth of the star-wheel with which it is shown engaged, permitting it to fall

back immediately and soon enough to engage the next spur of the star-wheel. The energizing of the escapement-magnet takes place through a circuit that includes the private-disk-wiper and any private-disk-¹⁹ segment with which it is engaged. This energizing occurs only when the private-disk-wiper meets a private-disk-segment with a guarding potential. One segment, by being connected with such a potential, ⁷⁵ permits the star-wheel to escape one notch, and two segments side by side thus guarded permit an escapement of two notches, etc.

The "first-selector" may be of a well-known type. The first-selector shown is of the general type shown in Patent No. 815,321, granted March 13, 1906, to Keith, Erickson & Erickson. In Fig. 17 the shaft 150 is shown carrying the line-wipers 151 and 152 and the private-wiper 153. These wipers are insulated from each other and from the shaft itself. On the upper section of the shaft there is a set of circular or so-called vertical-teeth 154, and another set 155 of longitudinal or so-called rotary-teeth, all on one piece 156 which is shrunk to the body of said shaft. The former teeth are comprised in the means by which the shaft is raised and locked, and the latter are included in the means by which the shaft is rotated and retained in any rotated position. The circular teeth are traversed by a groove 157 designed to engage the end of the shaft-rest or dog 158 which supports the shaft whenever the latter is rotated. Just below the ratchet-teeth-hub 156, a cam-piece 159 is fitted to the shaft and held in position by the tightening screw 160, the cam-piece being of a split sleeve form. To the top of the switch a guide-pin 161 is screwed; said pin holds one end of a coiled spring 162, the other end of which is fastened to the shaft. The spring is designed to give the shaft a return or back rotation, but the shaft is kept in normal rotary position by the stop or guide-arm 163 which, when the switch is not in use, is kept against the guide-pin or normal-post by the tension in said coiled spring. The guide-arm or normal-post 163 controls a contact-spring 164 with respect to the contact-point 165, for purposes hereinafter set forth.

The switch as a whole is directly operated through the medium of the line-relays 170 and 171, so long as it has not trunked through to another switch, and being of the trunk-release type surrenders control of its operative parts to the switch to which it trunks. The line-relays control the operative parts through the medium of the armatures 172 and 173 and the line-relay-springs 174, 175 and 176. Whenever the vertical-line-relay is operated the vertical-magnet 180, which is composed of two coils ¹²⁰ ¹²⁵ ¹³⁰

181 and 182, is energized. The said magnet is secured to the switch-frame and has opposite its free ends the vertical-armature 183 pivotally secured to the switch-frame by means of the pivots 184 and 185. The said armature vibrates up and down, being drawn up when the vertical-magnet is energized and restored when said magnet becomes de-energized by the retracting-spring 186 which is fixed to the vertical-arm by one end and by the other to the switch-frame. The vertical-armature carries a pawl 187 on its end, said pawl being held in normal position by a small retracting-spring 188, which latter has one end secured to the vertical-arm 189 and the other to the rear end of said pawl. This pawl is slotted between its pivot flanges, and through said slot the end of the vertical-arm protrudes. Said slot is short enough to prevent the retracting-spring 188 from drawing the upper end of the pawl too far in a forward direction. On its under side the vertical-arm carries an L-shaped piece 190 that comes into use 25 in unlocking the switch at the first vertical impulse of the vertical-armature. The release-magnet 195 is shown with only one coil. This is done to simplify the drawing; but in practice the release-magnet, like the vertical-magnet, is composed of two coils. The armature 196 of this release-magnet, known as the release-armature, is suspended from the switch-frame by the pivot-points 197 and 198 that afford said armature the means whereby it may vibrate about a horizontal axis that passes through said points. Said armature is under control of the retracting-spring 199 which normally keeps it away from the release-magnet. The forward end of the link 200 broadens out and has a square aperture 201 which is designed to engage with the so-called double-dog 202. Said double-dog is supported in a vertical plane from the switch-frame by means of the pivot-pieces 203, and has in its front part two angled arms 204 and 205 which, in the order named, act as locking-dogs for the shaft and work in conjunction with the respective circular and longitudinal teeth 154 and 155. When in use the locking-dogs are kept against the shaft by the retracting-spring 169. The lower section of the double-dog consists of an arm 206 which projects downwardly and which meshes with the link 235 to aid in the restoration of the side-switch after it has been used. On its rearward side, the double-dog carries a horizontal projection 207 having on its upper side a pin 208. It is through the medium of said pin that the release-link 200 locks with the double-dog whenever the former is thrust forward enough to cause the opening 201 to fall over said lug. The double-dog is normally retained by said link away from the shaft-teeth by the pull of the release- 30 armature retracting-spring 199. Whenever the vertical-magnet 180 is magnetized, the vertical-armature is attracted and the shaft is raised. At the first impulse of the vertical-armature the double-dog-link is raised and disengaged from the double-dog. At the same time the vertical-pawl 187 engages with one of the circular-teeth 154 and raises the shaft. While the shaft is in this raised position, the double-dog, upon being freed from the controlling influence of the release-link, moves the dog 204 under one of the circular teeth and thus insures the retention of the shaft in its new or raised position. As soon as the vertical-magnet becomes de-energized, of course, the vertical-armature, due to the pull of the retracting-spring 186, returns to its normal position, but the shaft itself is caught and held by the arm 204, as stated. When the rotary-line-relay is energized, the private-magnet 209 is thereby energized. This magnet is usually fastened to a small private-magnet-frame that is not shown and which is fastened to the main switch-frame. The private-magnet has an armature 210 that works in a vibratory manner about a horizontal axis that passes through the supporting points 211 and 212. Said armature is formed with a forwardly-projecting arm 213, the latter having two flat surfaces in an approximately horizontal plane. Furthermore, the end of the said arm is bent downwardly at right angles and carries certain mechanical details, namely, a lateral arm 214 which is designed to control the relation of the private-springs 215, 216 and 217 and a tooth-escapement which includes two flexible springs 218 and 219, each of which is riveted by one end to the arm 213, one on the upper side and the other on the lower. The upper spring is straight and has formed on its end two tooth projections 220 and 221 which extend down, while the former one is bent down and at right angles again to the front. This double angle on the lower spring is so designed that the latter may clear the bent portion of the private-arm against which portion said spring rests with some degree of tension, and so that there may be space in front of said bent portion to receive two other tooth-shaped upwardly-projecting pieces 223 and 224 that are formed on the forward end of the escapement-spring, and which are situated close to the upper teeth but slightly to the rearward thereof. A retracting-spring 225, which has one end attached to the private-armature and the other end to the switch-frame, holds said armature normally away from the private-magnet-pole-piece. In conjunction with the escapement above described, there is an escapement-finger 230 which is in fact the right extremity of the so-called side-switch-arm 231. Said finger 35 40 45 50 55 60 65 70 75 80 85 90 95 100 105 110 115 120 125 130

is normally retained behind the rearmost tooth of the lower escapement-spring. The side-switch-arm has near the base of the escapement-finger a small lug 232 which is bent forward. The function of this lug is to control the stroke of the side-switch-arm when it passes from the first to the second position, at which time it strikes the cam-piece 159. The side-switch-arm may be 10 made to oscillate about a pivotal support 233, located near its middle, and carries to the left of its center a rearwardly-projecting member 234, which latter, on its extremity, also carries pivotally secured thereto a link 235. The other end of said link is bifurcated and engages with the lower extremity of the downwardly-projecting arm 206 of the double-dog. Very near the left end of the side-switch-arm there rises perpendicularly a shaft 236 which supports the side-switch-wipers 237, 238, 239 and 240. These wipers are rigidly secured to the side-switch-arm and, as a whole, may be made to assume one of the three positions. In each of 25 said positions each of these wipers engages one of a series of contact-points 241, 242 or 243; 244, 245 or 246; 247, 248 or 249; 250, 251 or 252. The side-switch-arm with all its associated parts constitutes the well-known 30 side-switch which, when in the first or normal position, retains the side-switch-wipers, in the order named, in engagement with the contact-points 241, 244, 247 and 250, respectively, and the escapement-finger 230 35 behind the tooth 223. In the second position these wipers, in the same order, are found in engagement with the contact-points 242, 245, 248 and 251, respectively, and the escapement-finger 230 behind the tooth 224; 40 and when in the third position in engagement with the contact-points 243, 246, 249 and 252, respectively, and the finger 230 against the side-switch-stop 253. The force that operates the side-switch-arm 231, in a 45 forward direction, resides in a retracting-spring 254, which latter is fastened by one end to the switch-frame, and by the other to the side-switch-arm. When the private-magnet is energized once, the private-armature is drawn down momentarily and restored. By this operation the escapement-finger 230 passes first from behind the tooth 223 onto the tooth 220, at the downward 50 stroke of the private-armature, and from behind the latter tooth at the return stroke. As soon as the escapement-finger clears this last notch, the retracting-spring 254 draws the side-switch to the second position, and the latter is stopped by the lug 232 striking the cam 159. When the side-switch-wipers pass to the second position, in contact with contact-points 242, 245, 248 and 251, the rotary-magnet 260 is energized, this magnet comprising two coils 261 and 262. 55 The rotating mechanism comprises the

rotary-armature 263, a circuit-interrupting-arm 264 that works in conjunction with two interrupter-springs 265 and 266, the rotary-armature-finger 267 that exercises a certain control over the private-armature, and lastly 70 the rotary-arm 268. This rotary-arm carries pivotally attached to its forward end the so-called rotary-pawl 269. Said pawl has attached to its rear end a small coiled spring 270 the other end of which latter is fastened to the rotary-arm, and which always restores the rotary-pawl to its normal position. At each rotary step of the shaft the locking-arm 205 falls into one of the longitudinal-teeth. Said locking-arm and longitudinal-teeth form the circular locking device. When the rotary-armature is energized, the rotary-pawl 269 meshes with the longitudinal-teeth 155, and the shaft is rotated until the rotary-armature 263 strikes the rotary-magnet-pole-pieces. The energizing-circuit of the rotary-magnet passes through the interrupter-springs 265 and 266, and when the rotary-armature is attracted they are separated by the interrupter-finger 264. 85 When the energizing-circuit is broken the rotary-armature is drawn to its normal position by the rotary-armature-retracting-spring 271. Under the switch parts, and close to the line-wipers, the line-terminal-contacts and the private-terminal-contacts are shown in banks 272 and 273, respectively, one above the other. The private-contact-terminals are each one electric conducting piece; but the line-contact-terminals are each 90 made of two metallic pieces, one over the other, and insulated from each other. When the shaft is raised and rotated, the wipers engage with the contacts of their respective banks, the private-wiper with those of the private-bank, and the line-wipers with those of the line-bank. After the switch has been used it can be released—that is, restored to its normal position, by the energizing of the release-magnet 195 by simultaneously energizing the line-relays 170 and 171, or by magnetizing the back-release-relay 274 that controls the back-release-relay-springs 275 and 276. The circuits that are 100 brought into play under these conditions will be described. When the release-armature is drawn back, after the release-magnet loses its magnetizing force, the double-dog is drawn away from the shaft 150. The shaft, if it has been raised and rotated, rests on the shaft-rest 158 and, being left to the back pull of the coiled spring 162, it rotates on the shaft-rest until the stop-arm or normal post 163 strikes the guide or normal-post 161. The shaft-rest then enters the channel 157 that traverses the circular teeth, and leaves the shaft to fall to its normal position by its own weight. When the shaft is raised, this normal-spring 164 closes with 110 the contact-point 165, and in this way a 115

120

125

130

135

guarding potential is established at the "connector-private-banks" by way of the private-normal-conductor.

In mechanical details, the "connector" is very similar to the "first-selector", and many of the mechanical operations of the former are brought about by exactly the same methods, and through the same means, as in the latter. Said "connector" may be of any suitable type, but the one shown is of the general type described in Patent No. 815,176, granted March 13, 1903, to Keith, Erickson & Erickson. For instance, the "connector-shaft" 300 is the same as that of the "first-selector", having the line-wipers 301 and 302, the private-wiper 303, and the circular and longitudinal teeth 304 and 305, the circular teeth being traversed by the groove 306 adapted to receive the end of the shaft-rest 307. Below the piece upon which said teeth are cut, the cam 308 is fastened, while the coil-spring 309 performs the usual function, having one end fastened to the guide or normal-post 310. The guide or normal-post-arm 311 which retains the switch-shaft in its rotary normal position also controls the contact-spring 312 with respect to the contact-point 313. The "connector" has also a couple of line-relays 315 and 316 through the medium of which the operative parts of the "connector" may be controlled at all times by means of the armatures 317 and 318 and the line-relay-springs 319, 320, 321, 322 and 323. The vertical-magnet 325 in this switch has two coils 326 and 327, and is provided with a vertical-armature 328, which latter is supported from the switch-frame. This armature has a vertical-arm 329 which carries the vertical-pawl 330 and the L-shaped piece 331, all similar to the "first-selector". In the "connector" the release-magnet 335 is also represented as having but one coil; but it has two in practice, and is provided with its release-armature 336 on the right side of the magnet. This armature is also supported from the switch-frame and normally held away from the release-magnet-pole-piece by the retracting-spring 337 one end of which is attached to the release-armature and the other to the switch-frame. The said release-armature, instead of supporting the release-link 338 and thrusting the latter forward when the release-magnet is energized until the aperture 339 falls over the lug 340 of the double-dog 341, moves the latter until the lug 340 comes under the said aperture. This is done by means of the elongated section 342 on the said release-armature. The release-link is fastened rigidly to the "connector-switch-frame" and given a downward tendency by the retracting-spring 343 which may be secured in any desired manner. The double-dog, like that of the "first-selector", is supported in a vertical plane and vibrates

about the pivots 344 which support said double-dog in its place. The locking-arms 345 and 346 that work in unison with the circular and rotary teeth 304 and 305, respectively, are normally kept away from them. On its under side the double-dog is provided with an arm 347 which assists in releasing the side-switch and which, for this purpose, engages with the link 348. When the vertical-magnet is energized, the vertical-arm 329 and pawl 330 act as the similar parts do in the "first-selector", raising the shaft and lifting the release-link 338 from engagement with the double-dog, so that the latter may engage and hold the shaft after the vertical-arm falls. Whenever the rotary-line-relay is operated, the private-magnet 350 becomes active. This latter magnet is supplied with an armature 351 which carries a tooth-escapement that comprises the teeth 352, 353, 354 and 355 and the arm 356 that controls the private-springs 357, 358, 359 and 360. The mechanical structure and form of the private-armature of the "connector" is the same as that of the "first-selector", but the private-springs are differently arranged. The "connector" has a side-switch like the "first-selector", with the escapement-finger 361 working in unison with the escapement-teeth already pointed out. The side-switch-arm 362 carries the cam-lug 363 and the side-switch-wipers 364, 365, 366 and 367 which, in the order named, engage with the contact-points 368, 369, 370 and 371, in the first position; the contact-points 372, 373, 374 and 375 in second position; and the contact-points 376, 377, 378 and 379 in third position. The finger 361, of course, after it leaves the escapement-teeth, falls against the side-switch-stop-arm 380. The rotary-magnet 381 in the "connector" has two coils 382 and 383, like the rotary-magnet in the "first-selector"; but the armature 384 of the "connector" carries only a rotary-arm 385 and a rotary-pawl 386, which latter co-operates with the longitudinal teeth 305. The "connector" is provided with a back-release-relay composed of the two sub-relays 387 and 388 which, through their respective armatures 389 and 390, control the springs 391 and 392. When the release-magnet becomes energized, the release-armature 336 is attracted, and if the shaft happens to be raised and rotated the double-dog 341 is kicked inwardly, at which time the release-link 338 catches the former by the lug 339 and holds it out of the way of the ratchet-teeth on the shaft. The latter by its weight and by the tension of the coiled spring 309—as in the "first-selector"—falls to its normal position of rest. Beneath the switch are the line and private banks 395 and 396, respectively, with which the line and private wipers engage. The "connector-banks", of course, are of the

same form and structure as that described in connection with the "first-selector". A feature in the "connector" absolutely distinct from the "first-selector" is the ringer-relay 397, the armature 398 of which has supervision over the ringer-relay-springs 399, 400, 401, 402, 403 and 404. The ringer-generator has its two terminals 405 and 406 attached to two of said springs 401 and 404, 10 said generator being used for signaling purposes. Two condensers 407 and 408 are also used in connection with this switch and are included in the talking-circuits whenever a "connector" is used to call a subscriber's 15 line.

The sub-stations, such as one shown in Fig. 1, are of the usual type, or of any suitable type, each being provided with the necessary mechanical and electrical details 20 of a subscriber's station. Among said details there is, for instance, a receiver 410 in the secondary circuit and in series with the secondary winding of the induction coil 411. The usual position of said receiver is 25 on the switch-hook 412 which, when permitted to rise, opens a normally-closed circuit through the ringer 413 at the spring 414 when the lug 415 breaks away from the said spring. At the same time, the primary circuit-springs 416 and 417 and the ground-circuit-springs 418 and 419 and the secondary springs 420 and 421 are closed, the first 30 set when the lug 415 leaves the spring 414, the second set when the cam-finger 422 leaves the ground-spring 419, and the last 35 when the cam-finger 423 closes upon the spring 420. Whenever the receiver is replaced upon the switch-hook, the latter, upon its downward stroke, forces into contact 40 the so-called release-springs 424, 425 and 426, by means of another cam-finger 427 on said hook. This finger engages a projection allotted to these springs, which forms a 45 part of the spring 424. In the primary circuit the transmitter 428 is connected in series with the winding 429 of the induction-coil 411, the local batteries 430 and the primary circuit-springs 416 and 417. The 50 secondary circuit includes, besides the receiver and the secondary winding 431 of the induction-coil 411, a push-button 432 by which the spring 167 may be separated from the contact-point 166 and closed with the contact-point 435. In addition, the subscriber's station has a calling device composed of two push-buttons 436 and 437, the springs 438 and 439, and the contact-points 440, 441 and 442. For the purpose of operating the individual-switch, the switch-hook 55 412, which is connected with the rotary-line-conductor 3, is provided with an extra lug 443 which, when the switch-hook rises, after the receiver is removed, engages with a spring 444 that is connected with circuits 60 that lead to the ground. Upon the upward 65 movement of the switch-hook, and as soon as the ground-springs 418 and 419 come into contact, the ground-post 441 is placed in connection with ground over the following path: from the ground-terminal G¹, 70

through the springs 419 and 418, conductors 450, 451 and 452 to the ground-post 441. As the hook rises, the finger 443 meets the spring 444, after the said ground-circuit is closed, and a ground-impulse is set over the 75 rotary-line-conductor 3, and the rotary-line-relay 16 of the individual-switch C is energized. Said energizing-circuit may be traced from the grounded terminal G of battery B to the ground-terminal G¹ at the sub- 80 station A, then through the conductor 450, the spring 444, cam-finger 443, switch-hook 412, and conductor 454, contact-point 440, spring 438, through the rotary-line-relay 16, conductor 455, bridge-cut-off-relay-springs 85 456, 457 and 458, conductors 459, 460 and 461 to the nongrounded terminal of the battery B to ground G. As soon as said relay becomes magnetized, its armature 462 becomes attracted, and the springs 463 and 464 are brought into contact. The result 90 is that the release-magnet 28 of the individual-switch becomes energized through a path beginning with the grounded terminal G², through the springs 464 and 463, conductor 466, release-magnet 28, conductors 467 and 461, to the non-grounded terminal of battery B to the grounded terminal G. At once the armature 32 of the release-magnet 95 is attracted against the tension of the retracting-spring 42, and the wiper-carrier 41 of the individual-arm is left free. When the aforesaid armature is attracted, the lug 33 on the same clears the back surface of the locking-armature 25, and the notch on 100 the lower end of the latter falls over the said lug 33. This notched section is drawn over the said lug by means of the retracting-spring 27, so that when the magnetic impulse ceases to attract the releasing-armature 32, the latter is then not able to return 105 to its original position. Referring to Fig. 3, it is evident that if at the occurrence of the above operation the wipers are found in engagement with the first or innermost contact of the individual-bank 61, as shown in Fig. 4, and if the cam 46 is in such a position that the cam-drag 44 is out of alignment with the wiper-carrier 41, the former being driven to the right, as shown in Fig. 110 3, as soon as the releasing-armature 32 disengages from the ratchet-segment 40 on the said wiper-carrier, the latter, due to the tension of the coiled spring 54, is then rotated 115 along the bank-contacts until the individual-arm assumes a straight position similar to that indicated by the dotted lines in Fig. 4. The relation of the private-disk to the cams 120 is such that at whatever contact-point the wipers stop said contact will be the termi- 125 130

nal of an idle trunk-line, so that the privacy of the busy trunks is taken care of by the private-disk. Each segment of the private-disk is connected with an off-normal spring of a corresponding "first-selector", for instance, the segment 433 is connected with the off-normal contact 165 of the "first-selector" D the shaft of which is shown in Fig. 3. Whenever this "first-selector" is busy the corresponding segment is connected to ground. Now if the private-disk-wiper 125 is in engagement with the segment 470, after the latter becomes connected to the ground, the escapement device of the master-switch 13 which is controlled by the magnet 116 permits the shaft to rotate until the said wiper strikes the next segment 433 to the left. This last segment, if grounded, also causes (if the corresponding "first-selector" is busy) the shaft 12 to continue its escaping motion until the wiper 125 meets a non-grounded or non-busy segment. If the position of the private-disk-wiper 125, while in engagement with segment 470, corresponds to the position of the cam 46 (Fig. 3) which, when the individual-arm is free to move, will hold the individual-wipers in engagement with the tenth set of bank-contacts, as shown by the dotted lines in Fig. 4, then the position of the said wiper in contact with the next commutator-segment 433 will correspond to the position of the cam that will hold the individual-wipers in contact with the first set of bank-contacts shown in full lines in Fig. 4. Should said private-disk-wiper pass into contact with the next segment 434, then the cam 46 would be in such a position as to permit the individual-arm-wipers to rest in engagement with the second set of bank-contacts, and so on. Therefore, in whatever position the cam is found, such a position will insure the desired result, namely, that were an individual-arm set free at such time, the individual-arm-wipers will be stopped by the pin 60 striking the cam-drag 44, and in a position that will place said wipers in connection with an idle trunk-line. This trunk, as soon as the "first-selector" attached to it is operated, will be protected from seizure by any other individual-switch while it is busy by a ground guarding potential to the segment that corresponds to the said particular "first-selector", and at the same time will cause the shaft to rotate the cam to the new position. The circuits by which the above mechanical operations are attained will be described. If the subscriber at the sub-station A wishes to call the sub-station J, the number of which latter will be assumed to be #220, he will proceed to make the call. Now assume the private-disk-wiper 125 to be in engagement with the segment 470; then having removed the receiver from the hook and connected his line to an idle "first-selector" by the incidental operation of the individual-switch, as above described, which, when the wiper-carrier is set free, sets the wipers on the tenth set of bank-contacts, as shown by the dotted lines in Fig. 4, the calling subscriber is ready to begin to call by pressing the push-button 437 twice, and then pushing the button 436 once; then the first button again twice, and the second button once; for the last time the first button ten times, and the second button once. From what has already been stated it will be evident that were the calling subscriber to wait indefinitely after he removes the receiver from the hook before he presses the button 437 in the manner stated, any other individual-switch in the meantime may fall upon the same trunk-line and operate the "first-selector" in question, because no guarding potential appears at the proper private-disk-segment to advance the cam one step. At once a guarding potential will appear at the corresponding commutator-contact, and the cam 46 will be revolved to the next position, causing the individual-arm of the line of sub-station A to advance to a set of bank-contacts other than the set originally engaged—that is, if the cam of the individual-switch, at the time that the subscriber at the sub-station A removed the receiver from its hook, is in such a position that when the releasing-armature liberates the wiper-carrier, the latter will take the wipers to the tenth contact, as shown in Fig. 4, the private-disk-wiper 125 being in contact with the segment 470, and if in the meantime any subscriber of the same group of individuals should likewise raise his receiver from the switch-hook before the subscriber at the said sub-station A operates the shaft of the "first-selector" to which his line is connected (which latter act would place a guarding potential at the commutator-segment 470), the wipers of the individual-arm of the second individual in question would then also move to the tenth contact and assume a position similar to that shown by the dotted line in Fig. 4. Should the second subscriber in question at once begin to make the call, and thereby raise the shaft of the "first-selector," and thus ground the segment 470, he would cause the escapement device which controls the individual-shaft 12 to permit the latter to rotate and carry the private-disk-wiper to the next position, if said position is not busy. The individual-arm of the individual-switch being free, the cam-drag would shift from the position shown by the dotted lines in Fig. 4 to the position shown by the full lines in the same figure, by reason of the tension in the coiled spring 54. It is evident that the wiper-carrier would be taken to the first position, causing the individual-wipers to engage with the first set

of bank-contacts. It should be borne in mind, also, that should the first set of bank-contacts be in use at the time, there will also be a guarding potential at the commutator-segment 433, and the shaft would then rotate until said segment passes to the next contact, thus causing the individual-arm to carry the wipers to the contact 434. But assuming that the wipers do stop on the first set of bank-contacts, then when the subscriber eventually presses the push-button 437 two times, as was stated, the spring 439 is separated from the contact-point 442 and brought into contact with the ground-post 441. Said ground-post being already connected to the ground, through a circuit previously described, the vertical-line-relay 15 of the individual-switch C is energized twice. The circuit of the magnetizing-current extends from the ground G^1 at the substation, to the ground-post 441, over the conductor 2, through the vertical-line-relay 15, conductor 475, bridge-cut-off-relay-springs 457 and 458, conductors 459, 460 and 461, to the non-grounded terminal of battery B and to ground G. At the first impulse, the armature 476 becomes attracted, thereby causing the springs 477, 478 and 464 to be pressed into contact. Instantly, the locking-magnet 21 becomes energized, the current passing from the ground-terminal G^2 , through the springs 464 and 478, conductor 479, locking-magnet 21, conductors 480, 467 and 461, to the non-grounded terminal of battery B and to ground G. When this magnet 21 attracts its armature 25 it rotates the latter about the pivot-point 26, and thus releases the armature 32 from the end of the armature 25, permitting the former to regain its normal position, the end 43 of which re-engages with the ratchet-segment 40 and locks the wiper-carrier 41 with the first set of contacts of the bank 61, shown in full lines in Fig. 4. At the same time that the locking-magnet 21 becomes magnetized, the switching-relay 18 also becomes magnetized, the current passing from the ground-terminal G^2 through the springs 464 and 478, conductors 479 and 481, switching-relay 18, conductors 460 and 461, to the non-grounded terminal of the battery B and to ground G. This switching-relay, upon attracting its armature 482, causes the springs 483 and 484, and the springs 485 and 486, and likewise the springs 487 and 488, to close together, thereby extending the vertical and rotary line-conductors 2 and 3 to the vertical and rotary individual-wipers 58 and 59. At the instant that the springs 485 and 486 come into contact, the first grounded impulse that energized the vertical-line-relay 15, as explained, also causes at the same time the vertical-line-relay 170 of the "first-selector" to become magnetized over the following path: from the vertical-line-conductor 2, through the conductors 490 and 491, through the springs 486 and 485, conductor 492, through the vertical-wiper 58 of the individual-switch C, thence over the trunk-conductor 493, vertical-line-relay 170, conductors 495, 496 and 497, to the non-grounded terminal of battery B and to ground G. As soon as the vertical-line-relay 170 of the "first-selector" attracts its armature 172, the spring 174 is pressed against the spring 175, and the "first-selector-vertical-magnet" 180 becomes energized. This latter circuit extends from ground G^3 through the springs 175 and 174, conductor 498, private-springs 216 and 215, conductor 499, vertical-magnet-coils 182 and 181, conductors 500, 501, 502 and 497 to the non-grounded terminal of battery B and to ground G. In this way, the vertical-armature of the "first-selector" is attracted, thereby causing the vertical-pawl 187 to engage with one of the circular teeth 154 on the shaft 150, raising the latter one step. At the same time that the shaft is raised the L-shaped piece 190 unlocks the release-link 200 from the double-dog 207, and the latter, by the tension of the retracting-spring 169, is rotated until the arm 204 strikes the circular teeth 154, insuring the shaft against falling to the normal position. When the shaft is raised one step the off-normal spring 164, which is normally depressed by the guide-arm 163, is permitted to engage with the contact-point 165. As soon as said spring and contact-point engage, a guarding potential appears at the commutator-segment 433, by reason of being connected to ground over the conductor 503, through the contact-point 165 and spring 164, to ground G^4 . At the instant that said segment closed with ground the escapement-magnet 116, that controls the unwinding of the individual-shaft, is magnetized as long as the commutator-segment 433 and private-disk-wiper 125 are in contact. As soon as said magnet becomes energized the escapement-armature 119 (Fig. 10) is attracted, causing the pawl 124 which constitutes the other end of said armature to disengage from the star-wheel 118. The pawl 124 is the only mechanism that prevents the shaft from rotating, by engaging the star wheel 118, and when said pawl is disengaged from the star wheel by the magnet 116, the shaft is permitted to turn, as already explained. The private-disk-wiper 125 is so adjusted with respect to the engaging segments that immediately after the pawl 124 clears the spur 504 on the star-wheel 118, and before the shaft has moved the next spur on said star-wheel but a short distance toward the original position of the spur 504, the circuit through the said magnet 116 is broken, and the armature 119 is released in time for the pawl 124 to catch the succeeding spur. This

new position of the shaft places all of the cams on said shaft in such a position that the individual-arm of the next individual-switch that comes into operation will place its wipers in engagement with the second set of contacts of the terminal. Not only is there a guarding potential placed at the commutator-segment 433 when the shaft 150 of the "first-selector" is raised, but also at 10 the "connector-private-bank-contact" that corresponds to the number of the subscriber whose line terminates in the individual-switch C. This guarding potential is established from the ground-terminal G⁴ of the 15 "first-selector" D, through the off-normal spring 164 and the off-normal contact-point 165, conductor 503, to the segment 433 in one direction, and from contact-point 165 through conductor 505, wiper 57, conductor 20 506, springs 487 and 488, conductors 507 and 508 to the "connector-private-bank". Since the bridge-cut-off-relay 17 is bridged between the conductors 507 and 481, and since, when the vertical-line-relay 15 attracts its 25 armature 476, the conductor 481 becomes connected to ground through the ground-terminal G²; and since, when the "first-selector-shaft" permits the ground-spring 164 to close circuit with the contact-point 165 that places the conductor 505 in connection with ground through the ground-terminal G⁴, it is evident that as long as the vertical-line-conductor 2 is grounded after the "first-selector-shaft" is raised the bridge-cut-off-relay 30 17 is short-circuited through ground. However, as soon as the subscriber breaks the ground connection with the vertical-line-conductor at the end of the first impulse, the vertical-line-relay 15 becomes de-energized, and the armature 476 returns to its normal position, permitting the line-relay-springs 477, 478 and 464 to regain their normal positions. At the instant that the 35 springs 464 and 478 separate, the energizing-circuit through the locking-magnet 21 is interrupted, and the ground connection with the conductor 481 is removed, at which instant the bridge-cut-off-relay 17 becomes energized through the following circuit: from ground G⁴ at the "first-selector" D, thence to the conductor 505, wiper 57, conductor 506, springs 487 and 488, through the bridge-cut-off-relay 17, the line-switching-relay 18, and the conductors 460 and 461 to the non-grounded terminal of battery B and to ground G. In this circuit the line-switching-relay 18 and the bridge-cut-off-relay 17 are in series; the former, being previously magnetized to attract its armature, remains energized enough to hold together the springs which it controls, as already stated. The latter relay, upon being energized, separates the springs 456, 457 and 458 from each other, by means of its armature 314, removing thereby the connection between the rotary and vertical line-relays 16 and 15 of the switch C from the non-grounded battery connection, and at the same time removing the bridge formed by the rotary and vertical line-relays between 70 the rotary and vertical line-conductors 3 and 2, by separating the springs 456 and 457. It will be seen that the magnet 21 is also in series with the magnet 17, but this magnet 21 is of much lower resistance than the magnet 17, and does not operatively energize at this time. The removal of this bridge, at this particular instant, is designed to obviate the useless interruption of any voice-currents between the said line-conductors during a conversation, and to prevent any accidental or useless operation of said line-relays after a connection has been established. Now, when the button 437 is pressed the second time to complete the 75 operation corresponding to the first digit 2, the vertical-line-relay of the "first-selector" is energized once more, and the shaft 150 is raised one more step. In this way, the wipers upon said shaft of the "first-selector" are raised to the second level, opposite the first contact of the second row of their respective banks, but not in engagement therewith. At this stage of the 80 call, should the subscriber for any reason not wish to complete his call, he may restore the switches he has brought into use by restoring his receiver to its switch-hook.

85 On its downward course the switch-hook, by means of the releasing-cam 427, draws the so-called release-springs 424, 425 and 426 into contact, and they are held so for a moment. At the instant that these three 90 springs come into engagement the rotary and vertical line-conductors 3 and 2 are thereby simultaneously grounded, since the spring 426 is connected to the ground-terminal G¹ by way of the conductors 451 and 450, and through the ground-springs 418 and 419; and since the springs 424 and 425, respectively, are connected with the vertical and the rotary line-conductors, the former by the conductor 510 and the latter by the conductor 509, it is obvious that the 95 vertical-line-relay of the "first-selector" becomes energized. The rotary-line-relay 171 also is magnetized by current passing from ground-spring 426 over the rotary-conductor 3, conductors 513 and 514, springs 484 and 483, wiper 59, conductor 516, side-switch-wiper 240, rotary-line-relay 171 to battery B. Clearly, then, the rotary and vertical line-relays become energized simultaneously in the above operation. When the rotary-line-relay 171 attracts its armature 173 the private-magnet 209 becomes energized with the result that the private-spring-arm 214 separates the private-spring 216 from the private-spring 215 and closes it, instead, 100

105 110 115 120 125 130 135

with the lowest of these springs 217. When the vertical-line-relay presses the spring 174 against the grounded spring 175, after the private-magnet has thus changed the relation of the private-springs, the release-magnet 195 become magnetized by current flowing from the ground-terminal G^1 , through the springs 175 and 174, conductor 498, private-springs 216 and 217, conductors 511 and 512, release-magnet 195, conductors 500, 501, 502 and 497 to the non-grounded terminal of battery B and to ground G. This release-magnet, being thus energized, attracts the release-armature 196 in opposition to the tension of the retracting-spring 199. By this motion of the release-armature the release-link 200 is thrust forward and over the lug 203 on the double-dog 207. At the instant that the releasing-cam at the sub-station clears the release-springs, the connection of the line-conductors to ground is broken. The result is, of course, that the line-relays of the "first-selector" regain their normal positions, and the private-magnet as well. This last magnet, after losing its magnetic attracting force, permits the private-armature 210 to return to its normal position, thus permitting, in turn, the private-springs 217 and 216 to separate and thereby destroy the continuity of the energizing-circuit through the release-magnet 195. As soon as the release-magnet loses its power over the release-armature, the latter is returned to its normal position by the release-armature-retracting-spring 199. This spring, after the release-link engages with the double-dog, not only restores the release-armature to its normal position, but the double-dog 207 as well; and through the medium of the side-switch-releasing-arm 206 and the link 235 (with which latter the arm 206 engages) the side-switch is driven back to its first position, and, therefore, the side-switch-wipers into contact with the first set of contact-points; also, the escapement-finger passes to its corresponding position behind the rearmost escapement-tooth 223 of the lower escapement-spring 222. The switch-shaft, having been deprived of its locking support furnished by the double-dog-locking-arm 205, is set in motion in a backward direction in obedience to the tension of the clock-spring 162 which is designed to restore the said shaft to its normal position. The said back rotation is limited by the stop-arm 163, when the latter strikes the guide-pin or normal-post 161. At this juncture, the shaft-supporting-dog 158 breaks from engagement with the circular teeth 154, and enters the channel 157 that traverses said teeth; and at the same time the shaft-wipers leave the bank-contacts with which they have temporarily been in engagement. At this instant, the shaft loses its supports, and as a re-

sult it falls to the normal or released position in which it was found before it was disturbed by the operations of the subscriber. As soon as the shaft drops to its lowest point, the guide-arm 163 then separates the off-normal spring 164 from the contact-point 165, thereby removing the guarding potential described in connection with the corresponding private-disk-segment, and also breaks the circuit that provides the bridge-cut-off-relay 17 and line-switching-relay 18 with energizing-current for retaining their respective armatures. These two relays being thus restored, the individual-switch is restored and left in working condition, since at the restoration of the bridge-cut-off-relay-armature 314 the terminals of the individual-line-relays are restored to connection with the non-grounded terminal of the battery B. Continuing the call, instead of releasing, the subscriber, after grounding the vertical-line twice by pressing the button 437 twice, then presses the button 436 once, thereby energizing the rotary-line-relay 171 of the "first-selector" D. When this button is pressed the spring 438 is removed from the contact-point 440 and closed, instead, with the ground-post 441. The energizing-current passes from the ground-terminal G^1 at the sub-station A to the ground-post 441 and through the spring 438, thence over the rotary-line-conductor 3, conductors 513 and 514, through the springs 484 and 483 of the individual-switch, through the conductor 515, through the rotary-individual-wiper 59, thence over the trunk-conductor 516 to the rotary-side-switch-wiper 240, conductor 517, rotary-line-relay 171, conductors 496 and 497, to the non-grounded terminal of battery B and to ground G. When the rotary-line-relay-armature is attracted by the energizing of the rotary-line-relay, the springs 176 and 175 are placed in contact, and the private-magnet 209 becomes energized. The energizing-circuit passes through said magnet from the ground-terminal G^1 , through the springs 175 and 176, the conductors 518 and 519, private-magnet 209 and conductors 520, 502 and 497, to the non-grounded terminal of battery B and to ground G. The private-magnet being energized attracts its armature 210 and causes the side-switch-finger 230 to disengage from the rearmost tooth 223 of the private-armature-escapement-device, and to fall against the rearmost tooth of the upper escapement-spring 218. At the returning stroke of the private-armature 210, when the private-magnet becomes de-energized, this side-switch-finger again escapes to the front, this time from behind the upper tooth 220, and thus the side-switch-arm is drawn forward until the cam-lug 232 strikes the cam 159 and stops. This being the second position of the side-

switch, the side-switch-wiper 237 is then in engagement with the contact-point 242. As soon as said wiper closes with the contact-point 242 the energizing-circuit through the 5 magnet is completed from ground G, through the contact-point 242 and the side-switch-wiper 237, conductor 521, rotary-magnet-coil 262, interrupter-springs 265 and 266, rotary-magnet-coil 261, conductors 501, 10 502 and 497, to the non-grounded terminal of battery B and to ground G. When the rotary-armature is attracted the rotary-pawl 269 engages the longitudinal-teeth 155 on the shaft, and rotates the said shaft, so 15 as to cause the shaft-wipers to engage the first contact of the second level of their respective banks, at the same time that the rotary-armature-finger 267 strikes the private-armature and depresses the latter, 20 causing the foremost tooth 224 of the lower escapement-spring 222 to fall below the level of the lower side of the side-switch-finger 230. The shaft having been rotated, as stated, it follows, of course, that the cam 25 159 no longer serves as a stop for the side-switch-arm, the latter being drawn forward until the side-switch-finger falls against the lower foremost escapement-tooth. Not only does the rotary-armature advance the shaft 30 and depress the private-armature, but at the same time it drives the interrupter-finger 264 into engagement with the interrupter-springs 265 and 266, separating them and thereby breaking the continuity of the 35 energizing-circuit through the said rotary-magnet 260. The rotary-magnet becoming de-energized, the rotary-armature returns to its normal position, allowing the private-armature to be restored. At this time the 40 foremost tooth of the upper escapement-spring clears the escapement-finger and permits the side-switch to pass to the third position, the side-switch-arm 231 being now brought to rest against the side-switch-stop 45 253. The shaft does not return to its first position when the rotary-pawl is retracted from the longitudinal-teeth; for the double-dog 207, having been released from engagement with the release-link 200 at the first 50 vertical movement of the vertical-armature, upon the rotation of the shaft, falls behind one of said longitudinal-teeth and locks the shaft in its advanced position. It will be seen that as the shaft is rotated by the 55 rotary-armature the vertical-locking-dog 204 is withdrawn from engagement with the circular teeth 154 as the rotary-locking-dog 205 rides toward the crest of the first longitudinal-tooth, but at the same time the rest 60 158 engages the circular teeth and furnishes a support for the shaft in lieu of the vertical-locking-dog, and stays so as long as the shaft is retained in its rotary displaced condition. Of course, the interrupter-finger 264 eventually permits the interrupter-springs 65 265 and 266 to regain contact, but this does not occur until after the side-switch-finger has cleared the escapement-teeth, and the side-switch has passed into its third position, thus opening the circuit through the 70 rotary-magnet at the side-switch-wiper 237 and the contact-point 242 before said interrupter-springs re-engage. The side-switch now being in the third position, and the line-wipers being in engagement with the 75 first terminal of the second level of the line-bank, the subscriber's line is extended from the side-switch-wipers 239 and 240 through the contact-points 249 and 252, and conductors 523 and 522 to the line-wipers 151 80 and 152, and thence by way of a trunk-line similar to the trunk-line leading from the tenth terminal of the second bank-level (the conductors of which latter are designated as 524 and 525) to an idle "connector". 85

The vibration of the "first-selector-rotary-armature" may be continued indefinitely if the side-switch is detained in the second position. This should be clear from the foregoing, as when the interrupter-springs re-90 engage, after the rotary-armature returns to its normal position, the side-switch-wiper 237 being still in contact with the contact-point 242, the circuit through the rotary-magnet 260 will then be completed once 95 more. The side-switch when once in the second position may be retained there, even though the shaft be rotated, if the armature of the private-magnet be retained depressed; for as long as the foremost tooth of the 100 upper escapement-spring does not permit the escapement-finger 230 to pass, the side-switch cannot spring into the third position. In the system in connection with which our individual-switch is used, the "selectors" are 105 arranged in groups, one group of "first-selectors" to each group of individual-switches. In such groups of the "first-selectors" the banks, both private and line, are multiplied contact for contact. For example, if the selector D is the first one in the group to which it belongs, and there be also a second "first-selector" and a third "first-selector", etc., each of said "first-selectors" 110 is provided with bank-contacts similar to the bank-contacts 272 and 273 shown in Fig. 17. Furthermore, the first contact of the first level of the private-bank of the "first-selector" D is connected in multiple with the first contact of the first level of the private-bank of the second "first-selector", and with the first contact of the first level of the private-bank of the third "first-selector", and so on through the whole set. The same is 115 also true with respect to the private-bank-contacts of each of the other groups of banks. A similar arrangement is carried out with respect to the rotary and vertical contacts of the line-banks. For instance, 120 the vertical and rotary contacts of the first 125 130

terminal of the first level of the line-bank 272 are connected in multiple, respectively, with the vertical and rotary contacts of the first terminal of the banks of every succeeding "first-selector" in the same group, and so on. In the drawings (Fig. 17) the private-wiper 153, while the side-switch is in the second position, is connected through the back-release-relay 274 to the spring 176 under the control of the rotary-line-relay and is, therefore, at that time, connected in multiple with said spring to the same side of the private-magnet. It has been described how the calling subscriber, having removed his receiver, and pressed the button 437 twice, and then pressed the second button 436 once, has extended his line to the "first-selector" D, and operated the "first-selector", so as to raise the shaft of the latter to the second level and bring the private and line wipers into contact with the first terminal of the second level of their respective banks by rotating the shaft one step. At the instant this operation is accomplished, the private-wiper 153 is placed in connection with the ground-terminal of the grounded battery B and, therefore, the private-bank-contact with which it is engaged is also in connection with ground. The conductors over which this connection is completed are as follows: The private-wiper 153, conductor 530, the winding of the back-release-relay 274, conductor 531, side-switch-wiper 238, contact-point 246, the ground-terminal G, through ground to the grounded terminal of battery B. Said private-contact, being connected with ground through the private-wiper, becomes a point through which all other private-bank-contacts in multiple therewith attain connection with the ground-terminal of the battery B. It will be clear, then, that if nine "first-selectors" in the group to which the "first-selector" D belongs occupy, each one, a different one of the first nine positions of the second level of the "first-selector-banks", each one of the first nine private-bank-contacts in the second level of the group of the "first-selector" D will then be connected with ground. It was assumed in the description that has preceded that the rotation of the "first-selector-switch-shaft" 150 ceased as soon as the shaft-wipers were rotated into the first position. However, this will not be true if the first nine contacts of the second level of this same group are connected to ground by nine switches each occupying one of the first nine positions. Returning to the stage of the operation of the "first-selector" where the side-switch was tripped into second position, it can be shown that because the first nine private-terminals have guarding potentials, the rotation of the shaft will continue until the wipers reach the tenth contact. It will be remembered that the circuit through the rotary-magnet 260 is closed at that juncture when the side-switch-wiper 237 engages with the contact-point 242. At once, the rotary-armature is attracted by the rotary-magnet 260, and the shaft is rotated one step, bringing the shaft-wipers into engagement with the "first contact of the second level of their respective banks. The private-armature is depressed by the rotary-armature-finger 267, and the interrupter-springs 265 and 266 are separated by the interrupter-finger 264. The private-bank-contact with which the private-wiper engages, being connected to ground, caused the private-magnet to become energized. This energizing-circuit extends from the grounded terminal of the battery B, through some occupying-switch of the group to which the "first-selector" D belongs, and through the bank-multiplying conductors to the contact-point with which the private-wiper 153 is engaged, thence through the private-wiper 153, conductor 530, winding of the back-release-relay 274, conductor 531, side-switch-wiper 238, contact-point 245, conductors 532 and 519, private-magnet 209, and conductors 520, 502 and 497, to the non-grounded terminal of the battery B and to ground G. The private-armature is thereby retained in its depressed position, even after the energizing-circuit is broken at the interrupter-springs 265 and 266, and while the rotary-armature-finger returns to its normal position in response to the retracting tension of the rotary-armature-retracting-spring 271. It should be clear, then, that as soon as the interrupter-springs re-engage, the circuit through the rotary-magnet will then be closed again, and that the shaft will be rotated one more step by the re-energizing of the rotary-magnet 260. The private-wiper, of course, is driven into engagement with the second contact of the second level of the private-bank, and the line-wipers into engagement with the second set of terminals of the line-bank; but still the private-wiper meets a grounded guarding potential which retains the private-magnet energized, and thereby continues to retain the side-switch in its second position. Once more the interrupter-springs 265 and 266 are separated by the interrupter-finger 264, as the rotary-armature is attracted, and the energizing-circuit through said rotary-magnet is interrupted for the second time; then the rotary-armature 263 returns to its normal position. Obviously, the shaft will be rotated step-by-step as long as the private-wiper continues to be rotated into engagement with grounded private-bank-contacts. Having been rotated onto the ninth contact, the private-wiper is rotated one more step into engagement with the tenth contact of the second level; but this last contact being without a guarding potential, and as soon as

said private-wiper leaves the ninth contact, the energizing-circuit of the private-magnet that has up to this time held the side-switch in the second position is then broken. This 5 occurs at just about the instant when the rotary-armature is at the end of its forward stroke. This being true, the private-armature does not at once return to its normal position, but follows up the rotary-armature-finger 267, as the latter returns to its 10 normal place. At a given point the escapement-finger which has, during its operation, been resting against the foremost tooth of the upper escapement-spring, leaves said 15 tooth, and the side-switch as a whole is brought to the third position by the side-switch-retracting-spring 254, before the interrupter-springs have had time to re-engage. The side-switch being now in its 20 third position, the subscriber's line which was originally extended only as far as the "first-selector-side-switch-wipers" 239 and 240, before the side-switch sprang into its third position, is now extended to the line-wipers 151 and 152 by way of the conductors 25 252 and 523. The shaft having been raised two steps, vertically, and rotated ten points, the subscriber's line is not only extended to the said switch-wipers, but through the vertical and rotary contacts of the tenth terminal of the second level to the trunk-conductors 524 and 525 to the "connector" F. The restoration of the "first-selector" and individual-switches, as described, before the 30 "first-selector" was rotated, would be attained in the same manner, even should the "first-selector" be in the act of rotating—that is, even while the side-switch is in the second position; for it is clear that the release, as described, depends entirely on the energizing of the release-magnet 195 and, therefore, upon the simultaneous energizing of the line-relays 170 and 171 of the "first-selector" D. These relays remain in connection with the side-switch-wipers 239 and 240 and, therefore, with the extended line-conductors 493 and 516, until after the side-switch passes into its third position. However, after the "first-selector" has once operated, and the side-switch has tripped into the third position, the line-relays no longer remain in connection with the side-switch-wipers 239 and 240, since there is no connection between the contact-points 248 and 249, 35 nor between contact-points 251 and 252.

After the "first-selector" has trunked to the "connector", the release or restoration of said "first-selector", and of the individual-switch, is attained through the medium of the so-called back-release-relay 274. The line being extended to the "connector", when the subscriber again presses the first button twice, for the second digit, this again grounds the vertical-line-conductor twice and thereby operates the vertical-line-relay 40

315 of the "connector". This last energizing-circuit, beginning with the ground-terminal G¹ at the sub-station A and including the ground-post 441 and spring 439, extends over the vertical-line-conductor 2 to the vertical-side-switch-wiper 239 of the "selector" D, thence through the contact-point 249, the conductor 523, and the line-wiper 151, to the trunk-conductor 524, vertical-line-relay 315, conductors 535, 536, 537, 538, 539 and 540 45 to the non-grounded terminal of battery B and to ground G. When the vertical-line-relay of the "connector" attracts its armature 50 317, the latter causes the "connector-line-relay-spring" 320 to be pressed against the ground-spring 321. The vertical-magnet 325 is thereby energized, and the "connector-shaft" 300 is raised two steps. This energizing-circuit may be traced from the ground-terminal G¹, through the springs 321 and 320, the conductor 541, private-springs 538 and 537, conductor 542, side-switch-wiper 364, contact-point 368, conductor 543, vertical-magnet 325, conductors 537, 538, 539 and 540 to battery B and to ground G. 55

The vertical-armature of the "connector" and the "connector-shaft" being the same as similar parts of the "first-selector" D, the vertical movements of the shaft 300 will be understood. Of course, at the first vertical step of the "connector", the release-link 338 is unlocked from the double-dog 341 which, through the medium of the locking-dog 345, locks the shaft in its raised position. The two steps given to the shaft bring the wipers 60 opposite the first contact of the second level of their respective banks. The next thing the calling subscriber does is to press the rotary-button 436 once, thereby grounding the rotary-line-conductor 3, causing the rotary-line-relay 316 of the "connector" F to be operated. This energizing-circuit begins with the ground-terminal G¹, at the sub-station A, and extends through the ground-post 441, to the rotary-line-conductor 3, 65 thence to the side-switch-wiper 240 of the "first-selector", through the contact-point 252, conductor 522, rotary-line-wiper 152, rotary-trunk-conductor 525, "connector-rotary-line-relay" 316, conductors 536, 537, 538, 539 and 540 to the non-grounded terminal of battery B and to the grounded terminal G. 70 When the rotary-line-relay is attracted the latter presses the line-relay-spring 322 against the grounded spring 321, causing the private-magnet 350 to be energized. This circuit extends from the ground-terminal G¹, through the springs 321 and 322, conductor 544, private-magnet 350, and conductor 540 to the non-grounded terminal of the battery B and to the ground G. The private-magnet being operated, the side-switch-finger 361 escapes from the first to the second position, as described in connection with the "first-selector"; the side-switch-wipers 75

130

follow to a corresponding position, and the side-switch-wipers 364 and 365 engage with the contact-points 372 and 373, respectively. At the next operation, the vertical-push-button is pressed ten times, whereby the vertical-line-conductor 2 is grounded ten times, and, of course, the vertical-line-relay 315 of the "connector" is operated ten times over the circuit previously pointed out. At this time, the actuation of the vertical-line-relay, instead of operating the vertical-magnet 325, directs its work to the rotary-magnet 381, because of the shifting of the side-switch-wiper 364 from engagement with contact-point 368 into engagement with the contact-point 372. This latter circuit extends as above from the ground-terminal G⁷, through the springs 321 and 320, private-springs 358 and 357, side-switch-wiper 364, thence it takes a new path by way of the contact-point 372 and conductor 545, through the rotary-magnet 381, and through the conductors 539 and 540, to the non-grounded terminal of the battery B and to ground-terminal G. The operation of the rotary-magnet on the "connector" is very simple. Each time the rotary-armature is drawn forward by said magnet, the rotary-pawl 386 engages the longitudinal-teeth 305, thereby rotating the shaft one step at a time; the shaft is locked at each step by the rotary-locking-arm 346 of the double-dog 341, as in the "first-selector". Each time that this latter arm rides upon the crest of one of the longitudinal-teeth, the vertical-locking-arm leaves the circular teeth; but at the first rotary step, when the vertical-locking-arm disengages from the said circular teeth, the shaft-supporting-dog 307 comes into play and furnishes a substitute for holding the shaft in position. After the rotary-armature has rotated the shaft ten steps, the shaft-wipers are found at the tenth contact of the second level, and then the calling subscriber once more presses the rotary-button 436, thereby grounding the rotary-line-conductor once more, causing the rotary line-relay 316 of the "connector" to be energized again and, in turn, to operate the private-magnet as before. When the said private-magnet attracts its armature, the side-switch passes into its third position, connecting the calling subscriber's line with the called line, and putting a guarding potential upon the private-contact-point corresponding to the line which has been called, so that no other "connector" may venture on the same line. The connection between the two lines is completed from the vertical-trunk-conductor 524, through the condenser 407, conductor 546, ringer-relay-springs 402 and 403, vertical-side-switch-wiper 366, contact-point 378, conductor 547, vertical-line-wiper 302, normal-conductor 548, conductor 549, vertical-line-conductor 4, to the called sub-

station A, thence through the sub-station back over the rotary-line-conductor 5 and conductor 550, normal-conductor 551, rotary-line-wiper 301, conductor 552, contact-point 379, rotary-side-switch-wiper 367, ringer-relay-springs 400 and 399, conductor 553, condenser 408, to the rotary-trunk-conductor 525. Connected to the line-conductors 4 and 5 of the called sub-station J, shown in Fig. 2, there is an individual-switch H which is identical with the individual-switch C described and shown in Fig. 3. The bridge-cut-off-relay 554 is shown, with its bridge-cut-off-relay-springs 555, 556 and 557. The rotary and vertical line-relays 558 and 559 are also shown, as well as the line-switching-relay 560, the releasing-magnet 561, and the locking-magnet 562. The private-normal-conductor 563^a is similar to the private-normal-conductor 508 of the individual C and, like the latter, terminates in the "connector-private-banks" at the private-bank-contacts that correspond to the number of the sub-station #220 of the said individual. It was stated that a guarding potential was established at the private-bank-contact corresponding to the sub-station #220, at the instant that the side-switch of the "connector" passed into the third position. This guarding potential comes through the ground-terminal G⁸, and passes through the contact-point 377 to the side-switch-wiper 365, and thence over the conductor 563 to the private-wiper 303. This wiper, at this time, is in contact with the tenth private-contact of the second level of the private-bank 396 which is the private-contact that constitutes the terminal of the private-normal 563^a leading to the individual H. This guarding potential at this point sends current through the bridge-cut-off-relay of the individual H, for the purpose of opening up the line-relays 558 and 559 bridged across the normal-conductors 551 and 548. This magnetizing-current passes from the ground-terminal of the battery B to the private-wiper 303, over a circuit already described, thence over the private-normal-conductor 563^a, through the bridge-cut-off-relay 554, line-switching-relay 560, conductor 564, to the non-grounded terminal of the battery B.

The bridge-cut-off-relay becoming energized, the bridge formed by the line-relays across the normal-conductors 548 and 551 is opened up similarly to the bridge in the individual-switch C. The bridge in this last case, before the bridge-cut-off-relay is energized, extends from the normal-conductor 548, through the vertical-line-relay 559, normal-relay-springs 556 and 557, rotary-line-relay 558, to the rotary-normal-conductor 551. In the description of this call, it has been assumed that the called subscriber's line was found without meeting any obstructions; but it might have

been busy, either by having called another subscriber, or by having been called by another subscriber. In either case, there would have been a guarding potential at 5 the tenth contact of the second level of the private-bank, for reasons already mentioned. In the former case—that is, if the subscriber #220 had made a call—the said private-bank-contact would then have been 10 connected to ground through the off-normal-spring of whatever “first-selector” the individual-switch H would have selected, thence through the private-wiper 565 of the individual-switch and through the line-switching-relay-springs 566 and 567, to conductors 568 and 563^a, and to the “connector-private-bank-contact” in question. In the latter case, the guarding potential to the 15 “connector-bank” would have been furnished by the calling “connector” in the same manner described in connection with the “connector” F. Suffice it to say, however, that had there been such a guarding potential at the tenth contact of the second 20 level, at the instant when the calling subscriber pressed the rotary-button for the last time, to correspond to the digit 0, the “connector” F would have been released, and the calling subscriber #200 would 25 have failed to make the desired connection. This releasing would have resulted from the energizing of the “connector-release-magnet” 335. The conducting-circuit would 30 have extended from the ground-terminal of the battery B, through paths described, to the tenth contact of the second level of the “connector-private-bank”, through the private-wiper 303, conductor 563, side-switch-wiper 365, contact-point 373, conductor 569, private-springs 359 and 360, conductors 570 and 571, release-magnet 335, conductors 572, 538, 539 and 540 to the non-grounded terminal of the battery B and 35 to ground G. Of course, it is clear that at the time of the grounding of the rotary-line, as stated, due to the depressing of the private-armature 351, the private-springs 359 and 360 are in contact. The “connector-release-magnet”, being energized, the release-armature 336 is bound to move the double-dog 341 away from the shaft, which double-dog is then caught and locked by the release-link 338 in the manner already explained. The shaft being left clear, it 40 will drop to its normal or released position, like the “first-selector-shaft”. The calling subscriber, thinking he has established connection, presses the signaling-button 432 at the sub-station A with the result that the spring 165 is separated from the contact-point 166 and closes in contact with the contact-point 435. In this way, the vertical-line-conductor is connected to ground by 45 way of the ground-springs 419 and 418, from the ground-terminal G¹, thence to the contact-point 435, spring 165, secondary circuit-springs 421 and 420, contact-point 442, spring 439, to the vertical-line-conductor 2. The “connector” being released, the effect of grounding this vertical side 50 of the line is to operate the vertical-line-relay of the “connector”, which causes the vertical-armature 328 to be so operated as to raise the shaft 300, as before explained. As soon as said shaft rises from its normal 55 position, the spring 312, under the control of the guide-arm 311, closes in contact with the contact-point 313, and a busy-signal current is then sent over the line to the calling subscriber’s station, which busy-signal is produced by suitable means in the coil 573. This busy current passes from the coil 573, through the conductor 574, to the contact-point 313, spring 312, contact-point 371, side-switch-wiper 367, ringer-relay-springs 400 and 399, conductor 553, condenser 408, rotary-trunk-conductor 525, rotary-wiper 152 of the “first-selector” D, conductor 522, contact-point 252, thence 60 through the side-switch-wiper 240, to the rotary-trunk-conductor 516, rotary-wiper 59 of the individual-switch C, line-switching-relay-springs 483 and 484, conductor 514, rotary-line-conductor 3, spring 438, contact-point 440, conductors 455 and 575, receiver 410, secondary winding 431 of the induction-coil 411, contact-point 166, spring 167, springs 421 and 420, conductor 576, spring 439, vertical-line-conductor 2, conductors 490 and 491, line-switching-relay-springs 486 and 485, conductor 492, vertical-wiper 58, conductor 493, side-switch-wiper 239 of the “first-selector” D, contact-point 249, conductor 523, vertical-wiper 151, vertical-trunk-conductor 524, vertical-line-relay 315, back to the coil 573. The calling subscriber, under these conditions, will hear the busy-signal in his receiver, and recognizing the fact that the subscriber he has tried to call is busy, he 65 will then restore his receiver to its hook, and thereby momentarily and simultaneously ground both the rotary and vertical line-conductors. The result of grounding these conductors, it is evident, will be to simultaneously energize the rotary and vertical line-relays of the “connector” F. The rotary and vertical line-relays becoming magnetized simultaneously, the springs 319 and 323 are pressed into contact. These two springs are so adjusted that if the rotary-line-relay or the vertical-line-relay becomes energized alone, the said two springs do not come into contact with each other, but do so only when both the relays become active at the same time. As soon as these 70 two springs come into contact, the release-magnet 335 of the “connector” is then placed in series with the back-release-relay 274 of the “first-selector”, and these two become 75 80 85 90 95 100 105 110 115 120 125 130

energized at the same time by a current that passes from the ground-terminal G^o, at the "first-selector", to the contact-point 246, and thence through the side-switch-wiper 238, conductor 531, back-release-relay 274, conductor 530, private-wiper 153, release-trunk-conductor 576, springs 319 and 323 of the "connector" F, conductors 577 and 571, through the release-magnet 335, and thence to the non-grounded terminal of battery B and to ground G. As soon as the release-magnet 335 of the "connector" becomes magnetized, this switch is released, as before explained. In the "first-selector" 15 the back-release-relay, upon becoming magnetized, causes its armature 578 to press the back-release-relay-springs 275 and 276 together. The closing of these two springs completes a circuit through the "first-selector-release-magnet" 195, as follows: from ground G^o, through the back-release-relay-springs 276 and 275, thence through conductor 512, release-magnet 195, conductors 500, 501, 502 and 497, to the non-grounded 20 terminal of battery B. The "first-selector-release-magnet", by becoming momentarily magnetized, releases the "first-selector-switch". At the instant that the shaft 150 falls and separates the off-normal-springs 164 and 165, the relays of the individual-switch are restored in the manner previously described. However, if the calling subscriber at the sub-station #200 completes his connection with the sub-station #220, 25 without encountering any such obstacles as described, and when he presses the signalling-button 432, he grounds the vertical-line-conductor 2 and thus operates the vertical-line-relay 315 of the "connector" by current flowing over a familiar conducting path. This vertical-line-relay, upon being energized, presses the spring 320 against the spring 321, with the result, since the "connector-side-switch" is in third position, that the ringer-relay 397 is energized over a 30 circuit that may be traced from the ground-terminal G^o, through springs 321 and 320, conductor 541, through the private-springs 358 and 357, conductor 542, side-switch-wiper 364, contact-point 376, ringer-relay 397, conductors 579, 535, 536, 537, 538, 539 and 540, to the non-grounded terminal of battery B and to ground G. It will be seen that the ringer-relay-springs 399 and 402 35 constitute the terminals of the extended line of the calling subscriber, while the springs 400 and 403 constitute the terminal of the called line. Also, the springs 404 and 401 are connected directly to the brushes 405 and 406, respectively, of the ringer-generator K. Therefore, the ringer-magnet, upon becoming magnetized, causes its armature 398 to remove the springs 400 and 403 from the springs 399 and 402, and to press them into engagement with the springs 401 and 404, respectively. This operation places the called subscriber's line-terminals directly across the terminals of the ringer-generator K, which generator furnishes ringing-current that reaches the called subscriber's 40 station and energizes his ringing apparatus. The path of the ringing-current can be traced from the brush 406, through the ringer-relay-springs 401 and 400, through the side-switch-wiper 367, to contact-point 75 75 379, conductor 552, rotary-wiper 301, rotary-normal-conductor 551, conductor 550, rotary-line-conductor 5, spring 580, contact-point 581, conductor 582, switch-hook 585, thence through ringer-spring 584, the ringer 583, to the conductor 586, contact-point 587, spring 588, vertical-line-conductor 4, conductor 549, vertical-normal-conductor 548, "connector-vertical-line-wiper" 302, conductor 547, contact-point 378, side-switch-wiper 366, ringer-relay-springs 403 and 404, brush 405, back to the generator K. After hearing the signal, the subscriber at station #220 removes the receiver from the switch-hook 585, thereby removing the ringer 583 from across the line-conductors 4 and 5, and substituting in its place the talking-circuit which comprises the conductor 589, receiver 590, secondary winding 591 of the induction-coil 592, contact-point 593, springs 594 595 and 596, and conductor 586. 80 85 90 95 100 105 110 115 120 125 130

The local circuit that includes the battery 598 extends from said battery through the transmitter 599, local circuit-springs 600 and 601, primary winding 602 of the induction-coil 592, back to the battery 598. Of course, the answering subscriber upon speaking into the transmitter 599 induces talking-currents in the secondary winding 591 of the induction-coil 592, and in the receiver 590; and these two being bridged across the line-conductors 4 and 5 are connected with the line-conductors 2 and 3, which latter have also bridged across them the receiver 410 in series with the secondary winding 431 of the induction-coil 411. Clearly then, when these two sub-stations are thus connected their subscribers may readily communicate with each other, since the calling subscriber, by speaking into the transmitter 428, which is in circuit with the battery 430 and the primary winding 429 of the induction-coil 411, induces corresponding voice-currents in the secondary winding 431 which is in series with the receiver of the called sub-station No. 220, over circuits already described. After a connection between two subscribers has been thus established, the calling subscriber may restore the switches to their normal positions by hanging up his receiver and thereby causing the rotary and vertical line-conductors to be grounded at the same time. The grounding of these two conductors, as it has been pointed out, causes the "con-

nectar-line-relays" 315 and 316 to close in contact the trunk-release-springs 319 and 323. At that instant the "connector-release-magnet" 335, and "first-selector-back-release-relay" 274, are connected in series and energized. The former causes the restoration of the "connector-switch", while the latter releases the "first-selector", which "first-selector" upon dropping to its normal position separates the off-normal-springs 165 and 164 and thereby restores the individual-switch. Of course, it is clear that when once the "connector" F seizes upon the normal-conductors 548 and 551 that lead to the called sub-station, the said station is incapable of making a call as long as the said "connector" is bridged across the line of the called sub-station, because of the energized condition of the bridge-cut-off-relay 554 of the individual-switch to which the line is connected. Obviously, if for any reason a calling subscriber should fail to release the "connector", by neglecting to hang up his receiver, the called line would be maintained out of service indefinitely. To overcome this difficulty, the "connector" is provided with a back-release-relay comprising the two coils 387 and 388 which are provided with an armature 389 and 390, respectively. When these two armatures are attracted simultaneously, the back-release-relay-springs 391 and 392 are brought into contact, and by this means the release-magnet 335 of the "connector" may be energized by a current passing from the ground-terminal G¹⁰, through the back-release-relay-springs 391 and 392, through the conductors 577 and 571, through the release-magnet 335, and thence to the non-grounded terminal of battery B and to ground G. These two back-release-relay-coils may be energized by the called subscriber when the latter restores his receiver to the hook, at which instant the rotary and vertical line-conductors become grounded, in a well-known manner, through the medium of the release-springs 605, 606 and 607, which are operated by the release-cam 608. The circuits through each of these coils may be traced as follows: from ground G¹¹, through the ground-springs 610 and 609, conductor 611, to the release-springs 605 and 606, thence through the conductor 582 to the rotary-line-conductor 5, conductor 550, normal-conductor 551, rotary-wiper 301 of the "connector" F, contact-point 379, side-switch-wiper 367, ringer-relay-springs 400 and 399, conductor 553, relay-coil 388, conductors 535, 536, 537, 538, 539 and 540, to the non-grounded terminal of battery B; and on the other side from the release-spring 605, through the springs 606 and 607, contact-point 587, to the vertical-line-conductor 4, conductor 549, vertical-normal-conductor 548, vertical-wiper 302 of the "connector" F, conductor 547, contact-point 378, side-switch-wiper 366, ringer-relay-springs 403 and 402, conductor 546, coil 387, conductors 535, 536, 537, 538, 539 and 540, to the non-grounded terminal of battery B.

From the foregoing it is evident that when once the individual-switch seizes upon a set of bank-contact-terminals, and is locked therewith, the said wipers are not removed from engagement with said contacts, even after the individual-switch is restored, but remain in their original position until the individual-switch is operated again. The cam-drag, however, the instant it is unlocked, continues to be displaced to the right by the operation of the cam 46, and, as pointed out in the description of the individual-switch, the said drag is eventually locked behind the ratchet 47 by the pin 53 at the instant that the cam drives the cam-drag to its outermost position. In an exchange of 500 subscribers, the line groups, which are usually of twenty-five lines each, would aggregate twenty. In each group each of said lines would terminate in an individual-switch, such as the one shown in Fig. 12, mounted upon the angle-iron support 11. Therefore, each of said groups of lines would have associated with them a group of individual-switches, one to each line, and having a common sheaf, such as the shaft 12 shown in the drawings. Each of these shafts is provided with an automatic winding mechanism, such as the one described and illustrated in the drawings, and especially in Fig. 9. Accompanying each of said winding mechanisms, an escapement device is provided for each shaft, such as was illustrated and most clearly shown in Fig. 10. In addition, upon each of said shafts there is a cam similar to the cam 46, one for each individual-switch. Said cams are all situated in the same position—that is, if the shaft is in the position indicated in Fig. 3, and one of the cams is in the position illustrated by the cam 46, all other cams on this shaft are then similarly situated; so that if one cam-drag is engaging the tip of its corresponding cam, all other cam-drags resting on the surface are also engaging the tip of their corresponding cams. Upon the cams of one group there can be a maximum number of ten cam-drags at one time resting upon them. For instance, assuming that all of the cam-drags of some one group are locked, to begin with, behind the corresponding ratchets, similar to the ratchet 47 shown in Fig. 4, and that the shaft 12 is in such a position that as soon as the first individual-switch assumes a position similar to the position of the individual-arm shown in full lines in Fig. 4—at the bottom of the cam and locked there—and as soon as the "first-selector" operates its shaft vertically, then the escapement-magnet is energized

momentarily, because of the guarding potential established at the private-disk-segment with which the private-disk-wiper is engaged. The shaft then escapes one step, and since the wiper-carrier is locked, the cam-drag is rotated a little out of alignment with the wiper-carrier—corresponding to the degree of rotation given to the individual-shaft. Now when the second individual-switch of that group is operated it engages upon the second set of bank-contacts, where it is locked as soon as the second “first-selector” of that group is energized. At the same time, the individual-shaft escapes to the next position, thereby causing the cam-drags thus far on the cams of said shaft to be driven out a little further. Then if a third individual-switch comes into use, its wipers will engage the third set of bank-contacts, and at the instant that said wipers are locked in the said third position all of the cam-drags upon the cams will be driven out a little more, and in this way as many as ten individual-switches may come into operation in succession. When the individual-arm of the tenth individual-switch is set free, the wipers at once move into contact with the tenth bank-terminal, since the cams are by this time in the position shown in Fig. 3. As soon as the “first-selector” connected to said terminals is energized, the individual-shaft is rotated one more step, and all the cam-drags that are on the cams are locked at that instant. Now, since the ten trunks are busy, the ten segments of the private-disk are grounded, and the individual-shaft will continue to rotate until some one of the lines becomes idle; for the private-disk-wiper can find no segment that is not supplied with guarding potential. But if in the meanwhile one of the trunk-lines becomes idle, at the instant that the private-disk-wiper finds the idle trunk the rotation will stop, and the individual-shaft will stop with the cam in a position which will cause the next set of wipers that are brought into use to engage the said trunk that has become idle.

It will be seen that the cam-wiper 44 of each subscriber's individual-switch mechanism is controlled by a spring 44^a. With this arrangement, the said cam-wiper is always subject to spring tension tending to keep it against the cam. This spring and the cam-wiper and the cam constitute a part of the individual-switch mechanism, and compose what may be called the trunk-selecting means of such individual-switch. The movable contacts 57, 58 and 59 and the contacts of the banks 61 constitute what may be called the trunk-connecting means of the individual-switch—that is to say, the means whereby any selected trunk-line is closed in connection with the subscriber's line. It will be seen that the trunk-selecting means of any individual-switch is, when at rest, always in position for establishing connection with the next idle trunk-line—that is to say, the trunk-line next in order after the one last put in use. No subscriber whose line terminates at an individual-switch in this particular group can use his line and use his individual-switch without at the same time causing all other individual-switches in such group to simultaneously select the next idle trunk-line. Consequently, each subscriber, as he calls in and obtains connection with the trunk-line which his individual-switch has already selected for him, at the same time causes the switch-operating machine to rotate all of the cams 46 thereon, and to thereby set the trunk-selecting means of all idle individual-switches in selective relation to the next idle trunk-line. When another subscriber calls in, he will obtain connection with this selected trunk-line, and will also advance the shaft 12 another step, thus setting the trunk-selecting means of all idle switches in selective relation to another trunk-line. It will also be seen that the actuation of the shaft 12 not only gives the trunk-selecting means of all idle individual-switches a new position, but also produces a like condition with respect to the trunk-selecting means of all busy individual-switches. Suppose, for example, that one of the subscribers in the group calls in and obtains connection with the pre-selected trunk-line. When he does this, he also rotates the shaft 12 one step, thereby advancing all cams on this shaft one step, and consequently setting all switches distributed along this shaft, whether busy or idle, in selective relation to a new trunk-line—that is, in position for connection with the next idle trunk-line. Thus, each subscriber in making a call releases the trunk-connecting means of his individual-switch, and thereby obtains connection with the already selected trunk-line; but upon re-locking the connecting means he also readjusts or changes the condition of the trunk-selecting means of his individual-switch, and causes the same to assume a position or condition corresponding to the next idle trunk-line, and in so doing does the same thing to all other individual-switches distributed along the shaft. When a subscriber hangs up his telephone, and releases the connection between his line and the line of the called subscriber, he does nothing more to the individual-switch than simply de-energize one or more relays thereof, and simply leaves the trunk-connecting means of his individual-switch in the position which it assumed for the purpose of affording connection between his line and the trunk-line which he was to use in obtaining connection with the called subscriber. In other words, the trunk-connecting means of each sub-

scriber's individual-switch is adapted to remain in any position, and in a way does not have any normal position or condition, inasmuch as it can always be allowed to remain in any position corresponding to any one of the various trunk-lines. With respect to this feature of construction and mode of operation, it is desirable, as stated, that each individual-switch be so constructed that its 5 trunk-selecting means are operated and advanced to a point corresponding with the next idle trunk-line, whenever such idle switch is used by its allotted subscriber for completing connection with a previously selected trunk-line; for with this arrangement, a subscriber may use his switch for establishing a connection, may use the connection established with the called subscriber's line, may then hang up his telephone, thus breaking the connection and restoring all the switching apparatus, and may then immediately send in another call and obtain connection with another trunk-line, even though no other subscribers have 10 in the meantime sent in a call. In other words, each subscriber may use his individual-switch for completing a previously selected connection, and in so doing sets his individual-switch for connection with the 15 next idle trunk-line; and then if he subsequently sends in another call before a call is sent in by any other subscriber, he will then obtain connection with the trunk-line which his individual-switch selected in response to his first call. In this way, each 20 subscriber in making a call obtains connection with the already selected trunk-line, and at the same time selects another trunk-line for use by any subscriber making the 25 next call, whether such next calling subscriber be himself or some other subscriber. As explained, this automatic and mechanical selection of the next idle trunk-line, whenever any subscriber uses his individual-switch, takes place immediately upon the 30 seizure of the previously selected trunk-line; and, as shown and described, this automatic selection of the next idle trunk-line, whenever one of the individual-switches is used 35 for making the connection, takes place with respect to every individual-switch in the group, regardless of whether the same are busy or idle. Furthermore, the arrangement is not only such that each subscriber 40 is given a selective control over the individual-switches of all other subscribers in the same group, but is also, under certain conditions, given both a selective and a connective control over one or more other individual-switches in the same group. For 45 example, if a subscriber takes down his receiver, and then hesitates some time before proceeding to transmit the call, the trunk-line with which his switch has closed connection 50 may then be taken away from him, 55 so to speak, by the next subscriber making a call; for in such case there is as yet no guarding potential at the private-bank-contact in the individual-switch of the first subscriber, and the shaft has not as yet rotated 60 one step; and consequently all of the individual-switches in the group are still in selective relation to the trunk-line with which the first subscriber has closed connection. Under such circumstances, the second subscriber's individual-switch will make connection with the same trunk-line, and there will be a guarding potential at all private-bank-contacts corresponding to this trunk-line as soon as the second subscriber begins 65 making the call, and as soon as the "first-selector" which he gets closes the ground connection necessary for energizing the escapement magnet 116. When this is done, the shaft 12 rotates one step, thus bringing 70 all the individual-switches into selective relation to the next idle trunk-line; and as at this time the said first subscriber's individual-switch is only half through with its operation, so to speak, the magnet 28 being still 75 energized, it necessarily follows that the wiper-arm 41 of this first subscriber's individual-switch is free to move with the cam-wiper 44, so that in this case the connection with the next idle trunk-line is simultaneous with its automatic selection. More 80 simply stated, the arrangement is such that if a subscriber hesitates in calling, after getting connection with an idle trunk-line, another subscriber can then call in and cause 85 the individual-switch of the first subscriber to vacate the trunk-line with which it had made connection, and this trunk-line can then be appropriated for the purposes of 90 the second subscriber; but, of course, the second subscriber cannot thus appropriate for his own use a trunk-line with which connection has already been made by some other subscriber without substituting for such trunk-line one not then in use, and cannot disarrange the apparatus in such manner that the first subscriber will not have a "first-selector" connected with his line as 95 soon as he finally gets around to the point of calling the number of the desired subscriber. Of course, should there be no idle trunk-lines at the time that the already connected trunk-line is appropriated by the second calling subscriber, it is obvious, under such 100 conditions, that the first subscriber would be out entirely and would simply have to wait then until some one of the ten trunk-lines became idle; but the maximum number of calls sent in at any one time by a group 105 of subscribers can be readily determined, and a suitable number of trunk-lines can be accordingly placed at the disposal of the subscribers in such group, and the trunk-line service so arranged that the possibility of 110 all of the trunk lines leading from such 115 120 125 130 135 140

group of subscribers being busy at one time will be exceedingly remote, and practically precluded.

As explained, the shaft 12 is common to all of the individual-switches which are distributed along its length, but the maximum number of cam-wipers 44 which will be in engagement with their respective cams at any one time will, of course, depend upon the number of trunk-lines leading from the said switches. For example, if there are ten trunk-lines allotted to the use of the subscribers in this group, there will then never be more than ten cam-wipers resting upon their respective cams, inasmuch as there are only ten positions or steps in the operation of the said cams, with the result that if the trunk-lines are put in use, one after the other, the subscriber obtaining connection with the tenth trunk-line must of necessity throw all ten of the cam-wipers into their extreme or locked positions; and when the eleventh subscriber calls, his cam-wiper will then be the only one in contact with its allotted cam. Thus, there are a number of switches each of which is individual to a subscriber's line, and but one switch-operating machine for the entire group, this machine being common to all of the subscribers in the group and used by each for selectively operating the different switches. Consequently, each subscriber's individual-switch, whether in use or out of use, is always subject to a selective operation whenever any switch in the group is used for connective purposes. Obviously, the arm 41 constitutes a circuit-closing device for operating the trunk-connecting means, said trunk-connecting means consisting, as previously explained, of the wipers carried by said arm or circuit-closing device, and the line and private contacts in the bank 61. The said circuit-closing device is operated or impelled by spring means; for example, after the spring 62 has rotated the shaft one step, thus causing the individual-switch C to select the next idle trunk-line, it is the spring 54 which then actuates the arm 41 when the subscriber calls, and which moves the arm 41 to the selected position. It will also be seen that the spring 62 is, under certain conditions, capable of positively moving the arm or circuit-closing device 41 from one position to another—that is to say, the spring 62 is operative to simultaneously actuate the trunk-selecting and trunk-connecting means of the individual-switch C, as, for example, when the subscriber to whom this switch is allotted merely takes down his receiver and then hesitates before calling the number of the desired subscriber, thus permitting some other calling subscriber to come in ahead of him and obtain connection with the same trunk-line. The relays 18

and 17 remain energized during the use of the individual-switch for conversational purposes, and may be of 500 and 2000 ohms resistance, respectively; and it will be seen that the relay 18 controls the continuity of the talking-conductors extending between the line-wipers 58 and 59 and the line-wires 2 and 3. Furthermore, it will be observed that the arm or circuit-closing device 41, and in fact all of the trunk-selecting and trunk-connecting means of the individual-switch are adapted to remain at rest in position where last in use—that is to say, when the individual-switch C is released or restored it is only necessary to de-energize the relays 18 and 17, which is done by simply restoring the "selector" D and thereby separating the temporarily closed contacts 164 and 165. In this way, the trunk-connecting means of the individual-switch C are always closed in connection with some one of the trunk-lines and such trunk-line may be either busy or idle, and may be in use either by the switch C or by some other switch, inasmuch as there is no ground connected with the private-wiper 57, and no subscriber's line connected with the wipers 58 and 59, except when the relay 18 is energized and a "first-selector" raised one step. In this way, the wipers 57, 58 and 59 always remain where they were last put in use, and then simply advance to the next idle trunk-line as soon as the subscriber to whom the individual-switch C is allotted again takes down his receiver preparatory to making another call. With this arrangement, the "first-selectors" are provided with means and connections for establishing a guarding potential for the line of any calling subscriber, and for controlling the operation of the switch-operating machine E; for although each subscriber's line has an individual-switch, it will be seen that the guarding potential for preventing seizure of a calling subscriber's line is not established at the private-bank-contacts of the "connectors" having terminals of the subscriber's line until after the "selector" D, for example, is raised one step. Furthermore, the "first-selectors" as stated control the switch-operating machine E, and for this reason it is not until a "first-selector" is raised one step that the switch-operating machine is thrown into operation for the purpose of advancing all of the cams one or more steps and to a position corresponding with the next idle trunk-line. In other words, the calling subscriber uses his individual-switch for closing connection with the already selected trunk-line, but must then depend on the operation of the selected "first-selector" for setting the switch-operating machine E in operation, and for thereby properly operating all of the trunk-selecting means in the different switches of this particular group.

Moreover, the individual-switch C is provided with a pair of line-relays 15 and 16, the latter being adapted to control the energizing-circuit of the release-magnet 28, and the former employed for controlling the initial energizing of the vertical-line-relay of the "selector" D, and for controlling the initial energizing-circuit of the line-switching-relay 18 and the energizing-circuit of the unlocking-magnet 21. As soon as the "selector" is raised one step, the ground G⁴ is then substituted for the ground G² in the energizing of the line-switching-relay 18. The said two line-relays 15 and 16 can be of 500 ohms resistance each, and the magnets 21 and 28 can be of 60 ohms resistance each. It will be understood, however, that the resistance of the different magnets and relays can be changed or varied to suit the requirements of different cases, and can be adjusted for the purpose of obtaining the herein described operations. With this arrangement, the first number-impulse sent over the subscriber's vertical-line-conductor 2 accomplishes several things—to-wit, the raising of the "selector-shaft" 150 to the first level; the closure of the normally-open contacts 164 and 165; the supplying of energizing-current to the escapement-magnet 116; the energizing of the unlocking-magnet 21 and the consequent locking of the arm 41 in the selected position; the retention of the relay 18 in its energized condition, and the energizing of the relay 17; the establishment of a guarding potential over the calling subscriber's line; and all this, it will be seen, results simply from the momentary energizing of the vertical-line-relay 15, and from the consequent momentary closing together of the contacts 464, 477 and 478. In this way, the "first-selector" D and the line-relay 15 conjointly control the energizing of the relay means employed for controlling the continuity of the connection between the subscriber's line and the selected trunk-line.

It will be seen that the first vertical impulse transmitted by the calling subscriber serves to lock his individual-switch, give the "first-selector" its first vertical step, establish a guarding potential over the calling subscriber's line, operate the switch-operating machine, and effect the energizing of the bridge-cut-off and line-switching relays of the said individual-switch.

By "seizure" of a connection or line we mean the closure of connection with such connection or line, and the establishment of a guarding potential with respect to such connection or line, together with the temporary locking of the connecting means in the desired position.

From the foregoing it will be seen that we provide common automatic means by which one calling subscriber selects an idle trunk or

trunk-line for the next calling subscriber. We also provide subscriber's individual means for closing connection directly with the preselected trunks or trunk-lines. In this way each subscriber's individual trunking switch is always ready and in position to establish connection with a preselected trunk or trunk-line. By "always ready and in position" we mean, of course, that the switch is not only always in condition for use, but is always ready and in position to immediately close connection with an idle trunk-line, without the necessity of first making a step-by-step search for such idle trunk-line. In other words, we mean that each individual switch contains not only the means for closing electrical connection between a subscriber's line and the different trunks or trunk-lines, but also suitable automatic means for always keeping such circuit-closing or connecting means in selective relation to an idle trunk or trunk-line. In stating that each individual switch is always in position to close connection with an idle trunk-line, we mean that each individual switch contains at least one element for selecting or making a step-by-step search for idle trunks or trunk-lines, and that this element always has an idle trunk or trunk-line selected beforehand and ready and waiting to be seized by the next calling subscriber. In this way the establishment of connection with preselected trunk-lines is accomplished by switch contacts which are individual to the different subscribers' lines. Furthermore, it will be seen that we provide a system in which means are provided for automatically trunking calling lines into connection with called lines, in accordance with the numbers of the called subscribers, and in which the subscribers are provided with individual switches for automatically establishing connection with preselected trunks or trunk-lines running to said automatic trunking means. Consequently, there is, with our improved arrangement, a preliminary trunking operation which takes place in advance of the trunking operation by which the calling subscriber is given an idle connector on the proper board, which latter trunking operation is, of course, more or less under the control of the calling subscriber. The preliminary trunking operation, by which the individual switches of the subscribers are automatically operated to give each calling subscriber a preselected trunk-line, is purely automatic, and is in no way under the direction of the calling subscriber. With such arrangement automatic trunking is greatly facilitated, and the speed or rapidity with which calling lines are extended through the exchange and into connection with the called lines is greatly increased. It will be fully appreciated that in automatic or semi-automatic exchanges the faster the automatic

115

120

125

130

selection and connection can be made, the better the service.

- It will be observed that the arm 41 carrying the wipers is adapted to advance by a continuous or uninterrupted movement, and to reach the selected trunk without stopping. Should the preselected trunk be the last in the series, then the wipers traverse the entire series of trunk terminals by one continuous or uninterrupted movement. Suppose, however, that the wiper is resting on the preselected trunk, then in such case the calling subscriber gets the preselected trunk without moving the wiper of his switch, or those of any other switch. The wipers of several individual switches may accumulate on one trunk, and in time this trunk may become the preselected trunk—that is to say, the one calculated to be used by the next calling subscriber. In such case the first calling subscriber seizes the trunk to the exclusion of all the other subscribers, without moving any of the wipers. If the wipers of several of the individual switches have accumulated on one trunk, it will be seen that at such time a plurality of wipers are then connected in multiple to a single trunk, which trunk may in due course of service become the preselected trunk—that is to say, the trunk which will take the next call. In this way it is possible to have a preselected trunk with a plurality of subscribers' individual line wipers connected in multiple thereto. When the wiper carried by the arm 41 sweeps or jumps over the trunk terminals, it will be seen that both idle and busy terminals are quickly passed over, providing, of course, that some of the trunks in the path of the wiper are busy. Obviously, however, the continuous or uninterrupted jump or sweep of the wiper over a plurality of trunk terminals can be used for different purposes, and in different ways, without departing from the spirit of our invention.
- It will be seen that the subscriber's lines are each metallic circuit lines, inasmuch as they each provide a metallic circuit for talking. The trunk lines are of the same character, as each provides a metallic circuit for talking. When the subscriber hangs up, the relays of the connector are, as previously explained, controlled over the line circuit, and over the trunk line, to restore the connector and disconnect the subscriber's line from the trunk line. This also restores the subscriber's individual switch, but does not disconnect the wipers thereof from the trunk leading to the selector.
- What we claim as our invention is:—
1. An automatic telephone system comprising a plurality of subscribers' lines, a plurality of trunk-lines allotted to and common to said subscribers' lines, but less in number than the said subscribers' lines, together with an individual-switch for each

subscriber's line, and means common to all of said subscribers' lines for operating said switches, each switch being capable of establishing connection with any one of said trunk-lines, but always ready and in position to establish connection with an idle trunk-line while the subscriber's line is out of use. 70

2. A telephone system comprising a plurality of subscribers' lines, a switch for each subscriber's line, a plurality of trunk-lines, each switch having a series of trunk-line terminals each connected with one of said trunk-lines, and automatic means whereby the seizure of any trunk-line compels the switches of all idle subscribers' lines immediately to select the next idle trunk-line. 75

3. A telephone system comprising a plurality of switches each provided with a series of trunk-line-terminals, trunk-lines each connected with a terminal in each switch, and means whereby the seizure of any trunk-line compels all idle switches immediately to select the next idle trunk-line. 80

4. An automatic telephone system comprising a plurality of subscribers' lines, an individual-switch for each subscriber's line, a plurality of trunk-lines less in number than the subscribers' lines and each connected with all of said switches, automatic means for enabling any switch when operated to cause any and all idle switches to select the next idle trunk-line, whereby each switch is, when out of use, always ready and in position to establish connection between its allotted subscriber's line and an idle trunk-line. 90

5. An automatic telephone system comprising a plurality of subscribers' lines, an individual-switch for each subscriber's line, a plurality of trunk-lines less in number than the subscribers' lines and each connected with all of said switches, and electrically-operated automatic means for enabling each switch when put in use to cause any and all idle switches to select the next idle trunk-line, whereby each switch is, when not in use, always ready and in position to establish connection with an idle trunk-line. 105

6. An automatic telephone system comprising a plurality of subscribers' lines, a plurality of trunk-lines less in number than the said subscribers' lines, an individual-switch for each subscriber's line, each trunk line being connected with all of said switches, the said switches being each provided with a travelling circuit-closing device capable of establishing connection between its allotted subscriber's line and any one of said trunk-lines and the system also comprising automatic means whereby each circuit-closing device, when put in use, causes any and all idle circuit-closing devices to select an idle trunk-line, and where- 110

by each circuit-closing device is, when not in use, always ready and in position to establish connection between its allotted subscriber's line and one of said trunk-lines.

- 5 7. An automatic telephone system comprising a plurality of switches, a switch-operating means common to all of said switches and adapted for bringing about selective operations on the part of the same, 10 each switch including within itself suitable means for effecting a closure of any connection selected by the said switch-operating means, and automatic means whereby the seizure of any connection by any switch 15 causes any and all idle switches to simultaneously select the next idle connection, said switches being connected together and thus each adapted for closing any one of a certain number of normally-open electrical 20 connections.

8. An automatic telephone system comprising trunks, a plurality of trunking switches, a switch-operating means common to all of said switches and adapted for producing only trunk-selecting operations on the part of said switches, each switch comprising within itself suitable means for effecting a closure of connection with any trunk selected by the said switch-operating 30 means.

9. An automatic telephone system comprising a subscriber's line, a plurality of trunk-lines to be used by said subscriber in calling other subscribers, means whereby the same trunk-lines may be used by other subscribers, automatic circuit-closing means capable of establishing connection between the said subscriber's line and any one of said trunk-lines, and controllable by the said 35 subscriber, together with automatic means adapted and operative to produce a selective operation on the part of said circuit-closing means while the latter are idle and each time one of said trunk-lines is temporarily appropriated for use by some other subscriber.

10. The combination in a system employing normally deenergized individual relays for the subscribers' lines, of a calling subscriber's line, a plurality of trunk lines, an automatic switch individual to said subscriber's line for connecting the same with any one of said trunk lines, mechanism for preselecting an idle one of said trunk lines, means for maintaining said switch always ready and in selective position to connect said subscriber's line with a preselected idle trunk line while said switch is not in use, and relay means for said switch adapted to remain temporarily energized during the use of the switching means for talking purposes.

11. The combination in a system employing normally deenergized individual relays for the subscribers' lines, of a calling sub-

scriber's line, a switch individual to said line, a plurality of trunk lines leading from said switch, said switch being capable of establishing connection between the subscriber's line and any one of said trunk lines, mechanism for preselecting an idle one of said trunk lines, means for maintaining said switch in selective position to establish connection with a preselected idle trunk line while the subscriber's line is not in use, and relay means for said switch adapted to remain temporarily energized during the use of the switching means for talking purposes.

12. The combination, in a system employing normally de-energized individual relays for the subscribers' lines, of a plurality of subscribers' lines, a plurality of trunk-lines allotted to and common to said subscribers' lines, but less in number than the said subscribers' lines, an individual-switch for each subscriber's line, and means common to all of said subscribers' lines for operating said switches, each switch being capable of establishing connection with any one of said trunk-lines, but always ready and in position to establish connection with an idle trunk-line while the subscriber's line is out of use, the said switching means being provided with relay means adapted to remain temporarily energized during the use of the switching means for talking purposes.

13. The combination, in a system employing normally de-energized individual relays for the subscribers' lines, of a plurality of subscribers' lines, a switch for each subscriber's line, a plurality of trunk-lines, each switch having a series of trunk-line-terminals each connected with one of said trunk-lines, automatic means whereby the seizure of any trunk-line compels the switches of all idle subscribers' lines immediately to select the next idle trunk-line, the said switching means being provided with normally de-energized relay means adapted to remain temporarily energized during the use of the switching means for talking purposes, and means for so energizing said relay means.

14. The combination, in a system employing normally de-energized individual relays for the subscribers' lines, of a plurality of switches each provided with a series of trunk-line-terminals, trunk-lines each connected with a terminal in each switch, means whereby the seizure of any trunk-line compels all idle switches immediately to select the next idle trunk-line, the said switching means being provided with relay means adapted to remain temporarily energized during the use of the switching means for talking purposes, and means for so energizing said relay means.

15. The combination, in a system employing normally de-energized individual relays

- for the subscribers' lines, of a plurality of subscribers' lines, an individual-switch for each subscriber's line, a plurality of trunk-lines less in number than the subscribers' lines and each connected with all of said switches, automatic means for enabling any switch when operated to cause any and all idle switches immediately to select the next idle trunk-line, whereby each switch is, when out of use, always ready and in position to establish connection between its allotted subscriber's line and an idle trunk-line, the said switching means being provided with relay means adapted to remain temporarily energized during the use of the switching means for talking purposes.
16. The combination, in a system employing normally de-energized individual relays for the subscribers' lines, of a plurality of subscribers' lines, an individual-switch for each subscriber's line, a plurality of trunk-lines less in number than the subscribers' lines and each connected with all of said switches, and electrically-operated automatic means for enabling each switch when put in use to cause any and all idle switches to select the next idle trunk-line, whereby each switch is, when not in use, always ready and in position to establish connection with an idle trunk-line, the said switching means being provided with relay means adapted to remain temporarily energized during the use of the switching means for talking purposes.
17. The combination, in a system employing normally de-energized individual relays for the subscribers' line, of a plurality of subscribers' lines, a plurality of trunk-lines less in number than the said subscribers' lines, an individual-switch for each subscriber's line, each trunk-line being connected with all of said switches, the said switches being each provided with a traveling circuit-closing device capable of establishing connection between its allotted subscribers' line and any one of said trunk-lines, and the system also comprising automatic means whereby each circuit-closing device, when put in use, causes any and all idle circuit-closing devices to select an idle trunk-line, and whereby each circuit-closing device is, when not in use, always ready and in position to establish connection between its allotted subscribers' line and one of said trunk-lines, the said switching means being provided with relay means adapted to remain temporarily energized during the use of the switching means for talking purposes.
18. The combination, in a system employing normally de-energized individual relays for the subscribers' lines, of a plurality of switches, a switch-operating means common to all of said switches and adapted for bringing about selective operations on the part of the same, each switch including within itself suitable means for effecting a closure of any connection selected by the said switch-operating means, and automatic means whereby the seizure of any connection by any switch causes any and all idle switches to simultaneously select the next idle connection, said switches being connected together and thus each adapted for closing any one of a certain number of normally-open electrical connections, the said switching means being provided with relay means adapted to remain temporarily energized during the use of the switching means for talking purposes.
19. The combination, in a system employing normally de-energized individual relays for the subscribers' lines, of a plurality of switches, and a switch-operating means common to all of said switches and adapted for producing only selective operations on the part of said switches, but each switch comprising within itself suitable means for effecting a closure of any normally-open electrical connection selected by the said switch-operating means, the said switching means being provided with relay means adapted to remain temporarily energized during the use of the switching means for talking purposes.
20. The combination, in a system employing normally de-energized individual relays for the subscribers' lines, of a subscriber's line, a plurality of trunk-lines to be used by said subscriber in calling other subscribers, means whereby the same trunk-lines may be used by other subscribers, automatic circuit-closing means capable of establishing connection between the said subscriber's line and any one of said trunk-lines, and controllable by the said subscriber, and automatic means adapted and operative to produce a selective operation on the part of said circuit-closing means while the latter are idle and each time one of said trunk-lines is temporarily appropriated for use by some other subscriber, the said switching means being provided with relay means adapted to remain temporarily energized during the use of the switching means for talking purposes.
21. In a system for automatically trunking calling telephone lines into connection with called lines, having provisions by which each calling subscriber gets the first idle trunk line next in order after the one last in use, the combination of an idle subscriber's line, an idle trunk-line, and an individual-switch adapted for use by the calling subscriber in making any one of a number of possible connections, but temporarily retained in position to connect said lines when the subscriber calls, the said switching means being provided with suitable wiper means adapted when not busy to remain where last in use.

22. In a system for automatically trunking calling telephone lines into connection with called lines, having provisions by which each calling subscriber gets the first idle trunk line next in order after the one last in use, the combination of a calling subscriber's line, a plurality of trunk-lines, and an individual-switch capable of connecting the subscriber's line with any one of said trunk-lines, but always ready and in position to connect the subscriber's line with an idle trunk-line while the said switch is not in use, the said switching means being provided with suitable wiper means adapted when not busy to remain where last in use. 65

23. In a system for automatically trunking calling telephone lines into connection with called lines, having provisions by which each calling subscriber gets the first idle trunk line next in order after the one last in use, the combination of a calling subscriber's line, an individual-switch allotted to said line, a plurality of trunk-lines leading from said switch, the said switch being capable of establishing connection between the subscriber's line and any one of said trunk-lines, but also adapted and always in position to establish connection with an idle trunk-line while the subscriber's line is not in use, the said switching means being provided with suitable wiper means adapted when not busy to remain where last in use. 80

24. In a system for automatically trunking calling telephone lines into connection with called lines, having provisions by which each calling subscriber gets the first idle trunk line next in order after the one last in use, the combination of a plurality of subscribers' lines, a plurality of trunk-lines allotted to and common to said subscribers' lines, but less in number than the said subscribers' lines, an individual-switch for each subscriber's line, and means common to all of said subscribers' lines for operating said switches, each switch being capable of establishing connection with any one of said trunk-lines, but always ready and in position to establish connection with an idle trunk-line while the subscriber's line is out of use, the said switching means being provided with suitable wiper means adapted when not busy to remain where last in use. 95

25. In a system for automatically trunking calling telephone lines into connection with called lines, having provisions by which each calling subscriber gets the first idle trunk line next in order after the one last in use, the combination of a subscriber's line, a switch individual to said subscriber's line and provided with a series of trunk-line-terminals, and a trunk-line for each terminal, the said switch when out of use always having some one of said trunk-line-terminals selected and ready for use, said selected

trunk-line-terminal always being the terminal next in order after the terminal connected with the trunk-line last put in use, the said switching means being provided with suitable wiper means adapted when not busy to remain where last in use. 105

26. In a system for automatically trunking calling telephone lines into connection with called lines, having provisions by which each calling subscriber gets the first idle trunk line next in order after the one last in use, the combination of a plurality of subscribers' lines, a switch for each subscriber's line, a plurality of trunk-lines, each switch having a series of trunk-line-terminals each connected with one of said trunk-lines, and means whereby the use of any trunk-line compels the switches of all idle subscribers' lines to select the next idle trunk-line, the said switching means being provided with suitable wiper means adapted when not busy to remain where last in use. 120

27. In a system for automatically trunking calling telephone lines into connection with called lines, having provisions by which each calling subscriber gets the first idle trunk line next in order after the one last in use, the combination of a plurality of switches each provided with a series of trunk-line-terminals, trunk-lines each connected with a terminal in each switch, and means whereby the use of any trunk-line compels all idle switches to select the next idle trunk-line, the said switching means being provided with suitable wiper means adapted when not busy to remain where last in use. 135

28. In a system for automatically trunking calling telephone lines into connection with called lines, having provisions by which each calling subscriber gets the first idle trunk line next in order after the one last in use, the combination of a plurality of subscribers' lines, an individual-switch for each subscriber's line, a plurality of trunk-lines less in number than the subscribers' lines and each connected with all of said switches, automatic means for enabling any switch when operated to cause any and all idle switches to select the next idle trunk-line, whereby each switch is, when out of use, always ready and in position to establish connection between its allotted subscriber's line and an idle trunk-line, the said switching means being provided with suitable wiper means adapted when not busy to remain where last in use. 150

29. In a system for automatically trunking calling telephone lines into connection with called lines, having provisions by which each calling subscriber gets the first idle trunk line next in order after the one last in use, the combination of a plurality of subscribers' lines, an individual-switch for

each subscriber's line, a plurality of trunk-lines less in number than the subscribers' lines and each connected with all of said switches, and electrically-operated automatic means for enabling each switch when put in use to cause any and all idle switches to select the next idle trunk-line, whereby each switch is, when not in use, always ready and in position to establish connection with an idle trunk-line, the said switching means being provided with suitable wiper means adapted when not busy to remain where last in use.

30. In a system for automatically trunking calling telephone lines into connection with called lines, having provisions by which each calling subscriber gets the first idle trunk line next in order after the one last in use, the combination of a plurality of subscribers' lines, a plurality of trunk-lines less in number than the said subscribers' lines, an individual-switch for each subscriber's line, each trunk-line being connected with all of said switches, the said switches being each provided with a traveling circuit-closing device capable of establishing connection between its allotted subscriber's line and any one of said trunk-lines, and the system also comprising automatic means whereby each circuit-closing device, when put in use, causes any and all idle circuit-closing devices to select an idle trunk-line, and whereby each circuit-closing device is, when not in use, always ready and in position to establish connection between its allotted subscriber's line and one of said trunk-lines, the said switching means being provided with suitable wiper means adapted when not busy to remain where last in use.

31. In a system for automatically trunking calling telephone lines into connection with called lines, having provisions by which each calling subscriber gets the first idle trunk line next in order after the one last in use, the combination of a plurality of switches, a switch-operating means common to all of said switches and adapted for bringing about selective operations on the part of the same, each switch including within itself suitable means for effecting a closure of any connection selected by the said switch-operating means, and automatic means whereby the seizure of any connection by any switch causes any and all idle switches to simultaneously select the next idle connection, said switches being connected together and thus each adapted for closing any one of a certain number of normally-open electrical connections, the said switching means being provided with suitable wiper means adapted when not busy to remain where last in use.

32. In a system for automatically trunk-

ing calling telephone lines into connection with called lines, having provisions by which each calling subscriber gets the first idle trunk line next in order after the one last in use, the combination of a plurality of switches, and a switch-operating means common to all of said switches and adapted for producing only selective operations on the part of said switches, but each switch comprising within itself suitable means for effecting a closure of any normally-open electrical connection selected by the said switch-operating means, the said switching means being provided with suitable wiper means adapted when not busy to remain where last in use.

33. In a system for automatically trunking calling telephone lines into connection with called lines, having provisions by which each calling subscriber gets the first idle trunk line next in order after the one last in use, the combination of a subscriber's line, a plurality of trunk-lines to be used by said subscriber in calling other subscribers, means whereby the same trunk-lines may be used by other subscribers, automatic circuit-closing means capable of establishing connection between the said subscriber's line and any one of said trunk-lines, and controllable by the said subscriber, and automatic means adapted and operative to produce a selective operation on the part of said circuit-closing means while the latter are idle and each time one of said trunk-lines is temporarily appropriated for use by some other subscriber, the said switching means being provided with suitable wiper means adapted when not busy to remain where last in use.

34. The combination, in a system employing talking or voice-current conductors controlled as to their continuity by subscribers' individual relays, of an idle subscriber's line, an idle trunk-line, means for preselecting said trunk line, and an individual-switch adapted for use by the calling subscriber in making any one of a number of possible connections, temporarily retained in selective position to connect said lines when the subscriber calls, the said switching means being provided with talking-conductors, and with normally de-energized relay means for controlling the continuity of said conductors.

35. The combination, in a system employing talking or voice-current conductors controlled as to their continuity by subscribers' individual relays, of a calling subscriber's line, a plurality of trunk-lines, means for preselecting one of said trunk lines, and an individual-switch capable of connecting the subscriber's line with any one of said trunk-lines, always ready and in selective position to connect the subscriber's line with a pre-

selected idle trunk-line while the said switch is not in use, the said switching means being provided with talking-conductors, and with normally de-energized relay means for controlling the continuity of said conductors.

36. The combination, in a system employing talking or voice-current conductors controlled as to their continuity by subscribers' individual relays, of a calling subscriber's line, an individual-switch allotted to said line, a plurality of trunk-lines leading from said switch and means for preselecting one of said trunk lines, the said switch being capable of establishing connection between the subscriber's line and any one of said trunk-lines, and always in selective position to establish connection with a preselected idle trunk-line while the subscriber's line is not in use, the said switching means being provided with talking-conductors, and with normally de-energized relay means for controlling the continuity of said conductors.

37. The combination, in a system employing talking or voice-current conductors controlled as to their continuity by subscribers' individual relays, of a plurality of subscribers' lines, a plurality of trunk-lines allotted to and common to said subscribers' lines, but less in number than the said subscribers' lines, an individual-switch for each subscriber's line, and means common to all of said subscribers' lines for operating said switches, each switch being capable of establishing connection with any one of said trunk-lines, but always ready and in position to establish connection with an idle trunk-line while the subscriber's line is out of use, the said switching means being provided with talking-conductors, and with normally de-energized relay means for controlling the continuity of said conductors.

38. The combination, in a system employing talking or voice-current conductors controlled as to their continuity by subscribers' individual relays, of a plurality of subscribers' lines, a switch for each subscriber's line, a plurality of trunk-lines, each switch having a series of trunk-line-terminals each connected with one of said trunk-lines, and means whereby the use of any trunk-line compels the switches of all idle subscribers' lines to select the next idle-trunk-line, the said switching means being provided with talking-conductors, and with relay means for controlling the continuity of said conductors.

39. The combination, in a system employing talking or voice-current conductors controlled as to their continuity by subscribers' individual relays, of a plurality of switches each provided with a series of trunk-line-terminals, trunk-lines each connected with a terminal in each switch, and means whereby the use of any trunk-line compels all idle switches to select the next idle trunk-line,

the said switching means being provided with talking-conductors, and with relay means for controlling the continuity of said conductors.

40. The combination, in a system employing talking or voice-current conductors controlled as to their continuity by subscribers' individual relays, of a plurality of subscribers' lines, an individual-switch for each subscriber's line, a plurality of trunk-lines less in number than the subscribers' lines and each connected with all of said switches, automatic means for enabling any switch when operated to cause any and all idle switches to select the next idle trunk-line, whereby each switch is, when out of use, always ready and in position to establish connection between its allotted subscriber's line and an idle trunk-line, the said switching means being provided with talking-conductors, and with relay means for controlling the continuity of said conductors

41. The combination, in a system employing talking or voice-current conductors controlled as to their continuity by subscribers' individual relays, of a plurality of subscribers' lines, an individual-switch for each subscriber's line, a plurality of trunk-lines less in number than the subscribers' lines and each connected with all of said switches, and electrically-operated automatic means for enabling each switch when put in use to cause any and all idle switches to select the next idle trunk-line, whereby each switch is, when not in use, always ready and in position to establish connection with an idle trunk-line, the said switching means being provided with talking-conductors, and with relay means for controlling the continuity of said conductors.

42. The combination, in a system employing talking or voice-current conductors controlled as to their continuity by subscribers' individual relays, of a plurality of subscribers' lines, a plurality of trunk-lines less in number than the said subscribers' lines, an individual-switch for each subscriber's line, each trunk-line being connected with all of said switches, the said switches being each provided with a traveling circuit-closing device capable of establishing connection between its allotted subscriber's line and any one of said trunk-lines, and the system also comprising automatic means whereby each circuit-closing device, when put in use, causes any and all idle circuit-closing devices to select an idle trunk-line, and whereby each circuit-closing device is, when not in use, always ready and in position to establish connection between its allotted subscriber's line and one of said trunk-lines, the said switching means being provided with talking-conductors, and with relay means for controlling the continuity of said conductors.

43. The combination, in a system employing talking or voice-current conductors controlled as to their continuity, by subscribers' individual relays, of a plurality of switches, 5 a switch-operating means common to all of said switches and adapted for bringing about selective operations on the part of the same, each switch including within itself suitable means for effecting a closure of any 10 connection selected by the said switch-operating means, and automatic means whereby the seizure of any connection by any switch causes any and all idle switches to simultaneously select the next idle connection, 15 said switches being connected together and thus each adapted for closing any one of a certain number of normally-open electrical connections, the said switching means being provided with talking-conductors, and with 20 relay means for controlling the continuity of said conductors.

44. The combination, in a system employing talking or voice-current conductors controlled as to their continuity by subscribers' 25 individual relays, of a plurality of switches, a switch-operating means common to all of said switches and adapted for producing only selective operations on the part of said switches, but each switch comprising within 30 itself suitable means for effecting a closure of any normally-open electrical connection selected by the said switch-operating means, the said switching means being provided with talking-conductors, and with relay 35 means for controlling the continuity of said conductors.

45. The combination, in a system employing talking or voice-current conductors controlled as to their continuity by subscribers' 40 individual relays, of a subscriber's line, a plurality of trunk-lines to be used by said subscriber in calling other subscribers, means whereby the same trunk-lines may be used by other subscribers, automatic circuit-closing 45 means capable of establishing connection between the said subscriber's line and any one of said trunk-lines, and controllable by the said subscriber, automatic means adapted and operative to produce a selective operation 50 on the part of said circuit-closing means while the latter are idle and each time one of said trunk-lines is temporarily appropriated for use by some other subscriber, the said switching means being provided with talking-conductors, and with relay means for 55 controlling the continuity of said conductors.

46. A telephone system comprising a calling subscriber's line, a "first-selector", a 60 switch individual to the said line and adapted for automatically selecting and making connection with the said "selector", and terminal-banks having multiple terminals for connecting to said line, said "selector" being provided with means and con-

nctions for establishing a guarding potential at said banks to protect the calling subscriber's line against seizure by other subscribers.

47. A telephone system comprising a subscriber's line, an automatic selective switch individual to said line, a plurality of trunk-lines leading from said individual-switch, a step-by-step switching machine at the end of each trunk-line, and subscribers' means for operating said individual-switch and switching machines, each switching machine being provided with means and connections for establishing a guarding potential to protect the said subscriber's line against seizure by other subscribers when the line is in use. 70

48. A telephone system comprising a subscriber's line, a selective switch individual to said line, a plurality of trunk-lines leading from said individual-switch, a step-by-step switching machine at the end of each trunk-line, and subscribers' means for operating the said individual-switch and switching machine, each switching machine being provided with means and connections for establishing a guarding potential to protect the said subscriber's line against seizure by other subscribers while the line is in use, and each switching machine being adapted to establish such guarding potential upon 80 its initial operation. 85

49. A telephone system comprising a calling subscriber's line, a plurality of trunk-lines, automatic trunk-selecting machinery by which the subscriber's line may automatically connect with any idle trunk-line, and a step-by-step selective switching machine at the end of each trunk-line, each of said switching machines being adapted upon 90 its initial operation to establish a guarding potential for protecting the said subscriber's line against seizure by other subscribers while the line is in use. 95

50. A telephone system comprising a calling subscriber's line, automatic selective switching machinery, a plurality of trunk-lines each adapted to be connected by the switching machinery with the subscriber's line, and a step-by-step selective switching machine at the end of each trunk-line, each switching machine being provided with means and connections for establishing a guarding potential to protect the said subscriber's line against seizure by other subscribers while the line is busy, and each switching machine being also provided with means for protecting its trunk-line against seizure by other subscribers while such trunk-line is busy and connected with the 100 said subscriber's line. 110

51. A telephone system comprising a subscriber's individual trunk-selecting switch, a plurality of trunk-lines leading from said switch, a "first-selector" at the end of each trunk-line, and subscribers' means for oper- 120 125 130

- ating the individual-switch and "selectors", said individual-switch being provided with relay means adapted to remain energized during use of the switch for talking purposes, and each "selector" being provided with means and connections for controlling the energizing of said relay means. 65
52. A telephone system comprising a subscriber's individual trunk-selecting switch, a plurality of trunk-lines leading from said switch, a "first-selector" at the end of each trunk-line, a subscriber's line leading to the said individual-switch, and a "connector" provided with a line-terminal connected with said subscriber's line, said individual-switch being provided with a normally-closed bridge and a bridge-cut-off-relay, the energizing of which relay is controlled by both the said "connector" and the "selectors". 70
53. A telephone system comprising a subscriber's line, a normally-closed bridge across said line, a bridge-cut-off-relay, trunk-connecting means, a plurality of trunk-lines, and a line-switching-relay controlling the continuity of the connection between the line and the trunk-connecting means, and two energizing-circuits for said line-switching-relay, only one of said circuits including the winding of the bridge-cut-off-relay, and the resistance of the bridge-cut-off-relay being higher than that of the line-switching-relay. 75
54. A telephone system comprising a subscriber's individual trunk-selecting switch, and a plurality of trunk-lines with some one of which said individual-switch is always in connection whether busy or idle. 80
55. A telephone system comprising a trunk-selecting switch, and a plurality of trunk-lines with some one of which said switch is always in connection whether busy or idle, said switch having voice-current-conductors. 85
56. A telephone system comprising a group of subscribers' individual trunk-selecting switches, a plurality of trunk-lines leading from said switches, a single switch-operating mechanism common to all of said switches, a selector at the end of each trunk-line, and subscribers' means for operating said switches and "selectors", each "selector" being provided with electrical connections for controlling the operation of said switch-operating mechanism. 90
57. A telephone system comprising a trunk-selecting mechanism, and a plurality of trunk-lines leading from said mechanism, said mechanism being provided with a couple of arms pivotally connected together and subject to spring tension at their point of pivotal connection tending to keep them in alignment with each other, one of said arms being provided with a plurality of trunk-connecting switch-wipers, and there being also means for holding said wipers in any desired position, and a trunk-selecting cam for actuating the other arm. 95
58. A telephone system comprising a subscriber's line, and a trunk-selecting switch mechanism individual to said line, together with a plurality of trunk-lines leading from said individual-switch mechanism, said individual-switch mechanism comprising line-terminals connected with said trunk-lines, a couple of pivotal and spring-connected members, wipers carried by one of said members and adapted to traverse said line-terminals, means for temporarily locking said wipers in any desired position, and trunk-selecting means adapted to engage and operate the other member. 100
59. A telephone system comprising a group of subscribers' individual trunk-selecting switches, a plurality of trunk-lines leading from said switches, and a switch-operating machine common to all of said individual-switches, said switch-operating machine being provided with an operating-spring and with electro-magnetically-actuated means for winding up said spring, and for permitting the spring to unwind and operate the machine in a step-by-step manner. 105
60. A telephone system comprising a group of subscribers' individual trunk-selecting switches, a plurality of trunk-lines leading from said switches, a shaft along which said switches are distributed, a switch-operating machine common to all of said switches and adapted for giving said shaft a step-by-step rotation continuously in one direction, and a "first-selector" at the end of each trunk-line, each "selector" being provided with means and electrical connections for controlling the operation of said switch-operating machine. 110
61. A telephone system comprising a subscriber's line, a plurality of trunk-lines, and a subscriber's individual trunk-selecting and connecting switch provided with trunk-selecting means adapted for operation by other subscribers while the switch is out of use. 115
62. A telephone system comprising a subscriber's line, a plurality of trunk-lines, a subscriber's individual trunk-selecting switch for connecting the subscriber's line with any one of said trunk-lines, and means whereby the said subscriber's line when out of use is always held by the mechanism of said switch in selective relation to the next idle trunk-line. 120
63. A telephone system comprising a subscriber's individual-switch, a plurality of trunk-lines leading from said switch, subscribers' means for operating said switch, said switch having trunk-connecting means always resting in connective relation to the 125

trunk-line which was last used by the switch, and trunk-selecting means always resting in selective relation to the next idle-trunk-line.

64. A telephone system comprising a plurality of trunk-lines, and a trunk-selecting switch mechanism provided with a swinging arm, a plurality of wipers mounted on said arm, trunk-line-terminals adapted to be traversed by said wipers, a cam-wiper pivotally connected with said swinging arm, spring means suitably applied to the said arm and cam-wiper and tending always to straighten out or bring the same into alignment with each other, a rotary-cam for engaging said cam-wiper, spring means for holding the cam-wiper against said cam, a rack carried by said swinging arm, a pivoted dog adapted to engage said rack, an electro-magnet adapted when energized to draw the dog out of engagement with the rack, a latch for holding the dog out of engagement with the rack, an electro-magnet for releasing said latch, and relay means for controlling the energizing of said electro-magnets.

65. A telephone system comprising a plurality of subscribers' individual-switches, and a single switch-operating machine common to all of said switches and adapted for operating the same, said switch-operating machine comprising a shaft connected with the said individual-switches, a spring for operating said shaft continuously in one direction, an electro-magnetically-actuated device for winding up said spring, an electro-magnetically-operated escapement device for permitting said spring to unwind and thereby rotate the shaft in a step-by-step manner, and automatic electric switching means for controlling the operation of said escapement device, whereby all individual-switches are automatically set in selective relation to the next idle trunk-line when any one of said trunk-lines is temporarily appropriated for use.

66. An automatic telephone system comprising a switch subject to selective operations while out of use, and including means under the control of a subscriber for closing any normally-open circuit connection selected by the switch while out of use.

67. An automatic telephone system comprising a plurality of switching positions, and a circuit-closing device controllable by a plurality of subscribers for automatically selecting an idle switching position, but only controllable by a certain subscriber for purposes of using any selected position.

68. A telephone system comprising a ratchet device, an electro-magnet for actuating said ratchet device continuously in one direction, a bank of contacts, a switch-arm adapted to swing forward and back upon said contacts, so as to always engage one of said contacts, and transmitting connections

for converting the continuous rotation of said ratchet device into a forward and back movement on the part of said switch-arm.

69. A telephone system comprising an electro-magnetically-actuated ratchet device adapted for continuous rotation on one direction, a bank of contacts, and a member for engaging said contacts, and always in contact therewith, together with means for converting the continuous rotary motion of said ratchet device into a reciprocating motion on the part of said member.

70. A telephone system comprising subscribers' lines, an individual trunk-selecting mechanism for each line, a switch-operating mechanism common to all of said individual mechanism, subscribers' calling devices for transmitting the electrical impulses representing the number of any called subscriber, and automatic means whereby the first impulse transmitted by any calling device effects the operation of said switch-operating machine.

71. A telephone system comprising a calling subscriber's line, an individual trunk-selecting switch mechanism for said line provided with a normally-closed bridge, a bridge-cut-off-relay and a line-switching relay, the system also comprising a subscriber's calling device for transmitting the electrical impulses representing any called subscriber's number, together with automatic means whereby the first electrical impulse transmitted by said calling device effects the energizing of the said relays.

72. A telephone system comprising a calling subscriber's line, a subscriber's individual trunk-selecting switch mechanism for said line, trunk-lines leading from said individual-switch mechanism, a "first-selector" at the end of each trunk-line, a subscriber's calling device for transmitting the electrical impulses representing the number of any called subscriber, together with automatic means whereby the first impulse transmitted in calling any number effects a locking of the individual-switch in the desired position, as well as the establishment of a guarding potential for the calling subscriber's line.

73. A telephone system comprising subscribers' lines, an individual trunk-selecting switch mechanism for each line, trunk-lines running from the said individual-switches, a "first-selector" at the end of each trunk-line, a switch-operating mechanism common to all of said individual-switches, and subscribers' calling devices for transmitting the electrical impulses representing any called subscriber's number, together with automatic means whereby the first impulse transmitted in calling any number effects a locking of the individual-switch in the desired position, the establishment of a guarding potential for the calling sub-

scriber's line, and the operation of the said switch-operating machine.

74. A telephone system comprising a calling subscriber's line, an individual trunk-selecting switch mechanism for said line, a "first-selector" connected with the said individual switch, a subscriber's calling device for sending number-impulses representing the number of any called subscriber, and automatic means whereby the first number-impulse effects a locking of the individual-switch mechanism in position to maintain connection between the subscriber's line and the "first-selector", and also effects the initial operation of said "first-selector".

75. The combination of trunks, telephone lines, a bank of multiple trunk-terminals individual to each telephone line, means for connecting calling telephone lines with pre-selected idle trunks, including a swinging circuit-closing member or arm for each bank of terminals, and automatic means for selecting another idle trunk each time a pre-selected trunk is seized.

76. The combination of telephone lines, a plurality of trunks, a bank of trunk-terminals for each telephone line, a pair of line-wipers for each telephone line, a common means for selecting another idle trunk each time one is seized by a calling telephone line, and means for causing the wipers of any calling telephone line to spring into engagement with the terminal of the preselected trunk.

77. The combination of telephone lines, a plurality of trunks, individual trunking means for each telephone line, comprising means for connecting a calling telephone line with a preselected trunk, and a trunk-selecting mechanism common to all said individual means, comprising means for causing a mechanical trunk-selecting operation on the part of all idle individual means each time a preselected trunk is seized by a calling telephone line.

78. The combination of telephone lines, a plurality of trunks, an individual automatic trunking means for each telephone line, a common automatic trunk-selecting mechanism for producing a mechanical trunk-selecting operation in the individual means of all idle telephone lines each time a trunk is seized by a calling line, each individual means comprising means for connecting the telephone line thereof with the preselected trunk.

79. The combination of telephone lines, a plurality of trunks, automatic means for selecting another idle trunk each time one is seized by a calling telephone line, and means individual to each line for skipping or passing both idle and busy trunks and stopping at the preselected trunk.

80. The combination of trunks, a pair of line-wipers, automatic means for selecting

idle trunks, means for causing said wipers to skip or pass over both idle and busy trunks and stop on the preselected trunk, and a talking circuit including said wipers.

81. The combination of trunks, telephone lines all normally in selective relation to the trunk next in order after the one last in use, automatic means for selecting a new trunk for the idle lines each time a subscriber calls, and means individual to each line for connecting with the preselected trunk.

82. The combination of trunks, telephone lines, as many multiple terminals for each trunk as there are telephone lines, means individual to each telephone line for connecting with idle and preselected trunk terminals, a common mechanism for producing mechanical operations in the individual means of all idle telephone lines each time a preselected trunk is seized, to select a new trunk for the next call, said trunks less in number than said telephone lines.

83. The combination of trunk-terminals, step-by-step-operated means for selecting an idle terminal, a wiper, means for holding the wiper against movement while a selection is being made, and means for releasing the wiper to permit the same by one continuous movement to reach the selected terminal.

84. The combination of trunks, subscribers' lines, automatic means by which each calling subscriber selects an idle trunk for the next calling subscriber, including a step-by-step-actuated trunk-selecting member for each subscriber's line, and individual means for connecting calling subscribers' lines with the preselected trunks.

85. The combination of trunks, subscribers' lines, a set of trunk-terminals allotted to each subscriber's line, a movable terminal for each subscriber's line, each movable terminal provided with means for engaging any trunk-terminal in the set associated therewith, automatic means by which each calling subscriber selects an idle trunk for the next calling subscriber, and means for moving said line terminals into engagement with the preselected trunk-terminals.

86. In a telephone system, means for establishing a connection between a calling and a called subscriber's line, said means including a series of line terminals, lines leading from said terminals, a wiper adapted to travel over said terminals, means for selecting a position in said series of terminals ahead of the call, means for causing said wiper to reach the preselected position by one continuous uninterrupted movement, and means for extending said connection to find the called subscriber's line.

87. In a telephone system, a series of line terminals, lines leading from said terminals, a wiper adapted to engage said terminals, means for giving said wiper a continuous

uninterrupted movement over said terminals, means operative ahead of the call for varying the extent of said movement, a called subscriber's line, and means for extending said connection to find said called subscriber's line.

88. In a telephone system, subscribers' lines, a series of line terminals, lines leading from said terminals, a wiper adapted to travel over said terminals, means controlled over a subscriber's line by a relay normally at rest for giving said wiper a continuous uninterrupted movement over both busy and idle terminals, automatic means for predetermining and stopping the said movement of the wiper at any one of a plurality of points in said series, and means for extending connection to find the called subscriber's line.

89. In a telephone system, means for establishing a connection between a calling and a called subscriber's line, said means including a series of multiple trunk terminals, trunks leading from said terminals, an arm, means for causing said arm to pass busy and idle terminals by one continuous uninterrupted movement when a subscriber calls, means for stopping said arm at a predetermined point, and means for extending said connection to find the called subscriber's line.

90. In a telephone system, a plurality of trunks for talking purposes, and a subscriber's individual switch having a wiper always in engagement with one or another of said trunks.

91. In a telephone system, a plurality of trunks for talking purposes, and an automatic switch having a wiper always in engagement with one or another of said trunks.

92. In a telephone system, a plurality of trunks, automatic means for selecting an idle trunk ahead of the call, an idle wiper resting on the preselected idle trunk, and means for seizing said idle trunk without moving said wiper.

93. In a telephone system, a plurality of trunks, automatic means for selecting an idle trunk ahead of the call, a plurality of idle wipers all resting in connection with said preselected idle trunk, and means by which a calling subscriber seizes said idle trunk to the exclusion of all other subscribers without moving any of said wipers.

94. An automatic telephone system comprising an idle subscriber's line, a calling device associated with said line for transmitting operating impulses, an idle trunk line, a switch responsive to the impulses corresponding to the first digit of the called number and having vertical and rotary motion for extending connection from said trunk line, a switch individual to said subscriber's line and for use in making any one of a number of possible connections, and

means responsive to the first one of said impulses for temporarily retaining said individual switch in position to make connection between said lines when the subscriber calls.

95. A telephone system comprising a calling subscriber's line, a first-selector provided with means having vertical motion to select groups or divisions of the exchange and rotary motion to connect with a line in the selected group or division, a switch individual to the said line and adapted for automatically selecting and making connecting with the said selector, said selector being provided with means and connections for establishing a guarding potential to protect the calling subscriber's line against seizure by other subscribers.

96. A telephone system comprising a subscriber's line, an automatic selective switch individual to said line, a plurality of trunk-lines leading from said individual-switch, a step-by-step switching machine at the end of each trunk-line provided with means having vertical motion to select groups or divisions of the exchange and rotary motion to connect with a line in the selected group or division, and subscribers' means for operating said individual-switch and switching machines, each switching machine being provided with means and connections for establishing a guarding potential to protect the said subscriber's line against seizure by other subscribers when the line is in use.

97. A telephone system comprising a subscriber's line, a selective switch individual to said line, a plurality of trunk-lines leading from said individual-switch, a step-by-step switching machine at the end of each trunk-line, provided with means having vertical motion to select groups or divisions of the exchange and rotary motion to connect with a line in the selected group or division, and subscribers' means for operating the said individual-switch and switching machine, each switching machine being provided with means and connections for establishing a guarding potential to protect the said subscriber's line against seizure by other subscribers while the line is in use, and each switching machine being adapted to establish such guarding potential upon its initial operation.

98. A telephone system comprising a subscriber's line, a plurality of trunk-lines, automatic trunk-selecting apparatus by which the subscriber's line may automatically connect with any idle trunk-line, and a step-by-step selecting switching machine at the end of each trunk-line, provided with means having vertical motion to select groups or divisions of the exchange and rotary motion to connect with a line in the selected group or division, each of said switching machines being adapted upon its

initial operation to select a guarding potential for protecting the said subscriber's line against seizure by other subscribers while the line is in use.

99. A telephone system comprising a subscriber's line, automatic selective switching apparatus, a plurality of trunk-lines each adapted to be connected by the switching apparatus with the subscriber's line, and a step-by-step selective switching machine at the end of each trunk-line, provided with means having vertical motion to select groups or divisions of the exchange and rotary motion to connect with a line in the selected group or division, each switching machine being provided with means and connections for establishing a guarding potential to protect the subscriber's line against seizure by other subscribers while the line is busy, and each switching machine being also provided with means for protecting its trunk-line against seizure by other subscribers while such trunk-line is busy and connected with the said subscriber's line.

100. A telephone system comprising a subscriber's individual trunk-selecting switch, a plurality of trunk-lines leading from said switch, a first-selector at the end of each trunk-line, provided with means having vertical motion to select groups or divisions of the exchange and rotary motion to connect with a line in the selected group or division, and subscribers' means for operating the individual-switch and selectors, said individual-switch being provided with relay means adapted to remain energized during use of the switch for talking purposes, and each selector being provided with means and connections for controlling the energizing of said relay means.

101. A telephone system comprising a subscriber's individual trunk-selecting switch, a plurality of trunk-lines leading from said switch, a first-selector at the end of each trunk-line provided with means having vertical motion to select groups or divisions of the exchange and rotary motion to connect with a line in the selected group or division, a subscriber's line leading to the said individual-switch, and a connector provided with a line terminal connected with said subscriber's line, said individual-switch being provided with a normally closed bridge and a bridge-cut-off relay, the energizing of which relay is controlled by both the said connector and the selectors.

102. A telephone system comprising a subscriber's line, a normally closed bridge across said line, a bridge-cut-off relay, trunk-connecting means, a plurality of trunk-lines, a line-switching relay controlling the continuity of the connection between the line and the trunk-connecting means, two energizing circuits for said line-switching relay, only one

of said circuits including the winding of the bridge-cut-off relay, and the resistance of the bridge-cut-off relay being higher than that of the line-switching relay, and a vertical and rotary motion switch for each trunk-line.

103. A telephone system comprising a subscriber's individual trunk-selecting switch, a plurality of trunk-lines with some one of which said individual-switch is always in connection whether busy or idle, and a vertical and rotary motion switch for each trunk-line.

104. A telephone system comprising a trunk-selecting switch, a plurality of trunk-lines with some one of which said switch is always in connection whether busy or idle, said switch having voice-current conductors, and a vertical and rotary motion switch for each trunk-line.

105. A telephone system comprising a trunk-selecting mechanism, a plurality of trunk-lines leading from said mechanism, a vertical and rotary motion switch for each trunk-line, said mechanism being provided with a couple of arms pivotally connected together and subject to spring tension at their point of pivotal connection tending to keep them in alignment with each other, one of said arms being provided with a plurality of trunk-connecting switch-wipers, and there being also means for holding said wipers in any desired position, and a trunk-selecting cam for actuating the other arm.

106. A telephone system comprising a subscriber's line, a trunk-selecting switch mechanism individual to said line, a plurality of trunk-lines leading from said individual-switch mechanism, a vertical and rotary motion switch for each trunk-line, said individual-switch mechanism comprising line terminals connected with said trunk-lines, a couple of pivotal and spring-connected members, wipers carried by one of said members and adapted to traverse said line terminals, means for temporarily locking said wipers in any desired position, and trunk-selecting means adapted to engage and operate the other member.

107. A telephone system comprising a group of subscribers' individual trunk-selecting switches, a plurality of trunk-lines leading from said switches, a vertical and rotary motion switch for each trunk-line, and a switch-operating machine common to all of said individual-switches, said switch-operating machine being provided with an operating spring and with electro-magnetically-actuated means for winding up said spring, and for permitting the spring to unwind and operate the machine in a step-by-step manner.

108. A telephone system comprising a subscriber's individual-switch, a plurality of trunk-lines leading from said switch, sub-

- scriber's means for operating said switch, said switch having trunk-connecting means always resting in connective relation to the trunk-line which was last used by the switch, 5
5 trunk-selecting means always resting in selective relation to the next idle trunk-line, and a vertical and rotary motion switch for each trunk-line.
109. A telephone system comprising a calling subscriber's line, a subscriber's individual trunk-selecting switch mechanism for said line, trunk-lines leading from said individual-switch mechanism, a first-selector at the end of each trunk-line, provided with 10 means having vertical motion to select groups or divisions of the exchange and rotary motion to connect with a line in the selected group or division, a subscriber's calling device for transmitting the electrical impulses representing the number of any called 15 subscriber, and automatic means whereby the first impulse transmitted in calling any number effects a locking of the individual-switch in the desired position, as well as the establishment of a guarding potential for the calling subscriber's line. 20
110. A telephone system comprising subscribers' lines, an individual trunk-selecting switch mechanism for each line, trunk-lines running from the said individual-switches, a first-selector at the end of each trunk-line, provided with means having vertical motion to select groups or divisions of the exchange and rotary motion to connect with a line in the selected group or division, a switch-operating mechanism common to all of said individual-switches, subscribers' calling devices for transmitting the electrical impulses representing any called subscriber's number, 30 and automatic means whereby the first impulse transmitted in calling any number effects a locking of the individual-switch in the desired position, the establishment of a guarding potential for the calling subscriber's line, and the operation of said switch-operating machine. 40
111. The combination of trunks, a pair of line wipers, automatic means for selecting idle trunks, means for causing said wipers to skip or pass over both idle and busy trunks and stop on the preselected trunk, a talking circuit including said wipers, and a vertical and rotary motion switch for each trunk-line. 50
- 55 112. In a telephone system, a series of trunks having multiple terminals, an arm, means for causing said arm to pass both busy and idle terminals by one continuous uninterrupted movement when a subscriber calls, means for stopping said arm at a predetermined point, and a vertical and rotary motion switch for each trunk.
113. In a telephone system, a plurality of trunks for talking purposes, a subscriber's individual-switch having a wiper always in engagement with one or another of said trunks, and a vertical and rotary motion switch for each trunk. 65
114. In a telephone system, a plurality of trunks for talking purposes, an automatic switch having a wiper always in engagement with one or another of said trunks, and a vertical and rotary motion switch for each trunk. 70
115. In a telephone system, a plurality of trunks, automatic means for selecting an idle trunk ahead of the call, an idle wiper resting on the preselected idle trunk, means for seizing said idle trunk without moving said wiper, and a vertical and rotary motion switch for each trunk. 75
116. In a telephone system, means controlled by a subscriber for extending a call, said means including an idle trunk-line, means for selecting said trunk-line in advance of the call, an idle automatic switch wiper engaging said trunk-line, and means whereby the trunk-line is thereby made ready for talking purposes as soon as the subscriber calls. 80
117. In a telephone system, a non-numerical trunking switch, trunk lines for talking purposes leading therefrom, said switch having line wipers always in electrical engagement with some one of said trunk lines, which connected trunk line is always the one last employed by said switch for extending a call, a telephone line to which said switch is individual, and a normally deenergized relay controlling, on energization, the connection between the said telephone line and switch. 85
118. A telephone exchange system comprising a plurality of telephone lines, a plurality of associated link-circuits, a plurality of switch mechanisms individually operative to establish connection between a calling telephone line and an idle link-circuit, a wiper for each of said mechanisms, and means for rendering the selected link-circuit selectable by other switch mechanisms while still maintaining the wiper of the operated switch mechanism in engagement with said selected link-circuit. 90
119. In a telephone exchange, a circuit, stationary contact terminals therefor, a second circuit, movable brushes in which said second circuit terminates, a carriage for said brushes, a mechanical stop for said carriage, and means actuated upon the establishment of a certain electrical condition in said first mentioned circuit for projecting said stop into the path of said carriage. 100
- Signed by us at Chicago, Cook County, Illinois, this 11th day of October, 1905.

JOHN ERICKSON.
CHARLES J. ERICKSON.
